UNITED STATES PATENT OFFICE.

ALFRED H. DYSON, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed January 5, 1905. Serial No. 239,730.

To all whom it may concern:

Be it known that I, ALFRED H. DYSON, a citizen of the United States of America, and resident of Chicago, in the county of Cook 5 and State of Illinois, have invented a certain new and useful Improvement in Telephone Systems, of which the following is a specification.

My invention relates to automatic telephone systems in general; and it relates more particularly to automatic telephone systems in which the different subscribers' lines terminate in step-by-step switching mechanism or apparatus, said mechanism or apparatus being under the control of and employed by the subscribers, through the medium of suitable circuit-controlling devices at the subscribers' stations, for automatically establishing connection between any 10 calling subscriber's line and any desired called subscriber's line; and it also relates more especially to automatic telephone systems of the said particular character in which the switching mechanism or apparatus comprises a suitable number of so-called "selector-switches," through the medium of which any calling subscriber may establish connection with one or more trunk-lines, and comprising also a suitable number of so-called "connector-switches," through the medium of which a calling subscriber may, after having established the desired trunk-line connection, then make the final connection with the line of the called subscriber. 15

Generally stated, the object of my invention is to provide an improved automatic telephone system which will afford efficient and satisfactory service to different subscribers, and which will, at the same time, be 20 more economical to install and maintain.

A special object is to provide an improved construction and arrangement whereby, in an automatic telephone system of any suitable character, the current, both for talking 25 and signaling purposes, may be furnished from a common battery or other centralized source of current supply.

Another object is to provide an improved construction and arrangement whereby the current for both talking and signaling purposes may, in an automatic telephone system of the character to which my invention more particularly and especially relates, be furnished to the subscribers' lines through 30 the said so-called "connector-switches," and

from a common battery or other centralized source of current supply.

Another object, and one which constitutes a distinguishing and more or less specific feature of my invention, is to provide an improved construction and arrangement of such character that no closed metallic battery circuit will, in the process of connecting up one subscriber with another, be formed or established until the called subscriber answers the call. 60

Another object is to provide an improved construction and arrangement for releasing the switching mechanism and apparatus employed for connecting up one subscriber with another—that is to say, for restoring said switching mechanism or apparatus to its normal condition, and thus effecting a disconnection between subscribers' lines after the conversation is terminated. 70

An additional object is to provide an improved construction and arrangement for insuring the automatic removal or cutting off of certain bridges from the talking circuit, so that these bridges, which normally exist across the line conductors, and which contain the coils of relays or magnets, may be eliminated from the circuit during conversation between the subscribers, and are thus prevented from remaining across the talking circuit while the calling subscriber is completing the process of making connection with the called subscriber's line, and while the voice currents are traversing the finally established talking circuit. 75

It is also an object to provide certain details and novel features of construction, and certain features of improvement tending to increase the general efficiency and serviceability of an automatic telephone system of this particular character. 80

To the foregoing and other useful ends, my invention consists in matters hereinafter set forth and claimed.

In the accompanying drawings, the first four figures constitute a single diagram illustrating a calling subscriber's telephone and switching and signaling equipment connected with a similar equipment of a called subscriber's line; Fig. 1 being a diagrammatic representation of the calling subscriber's apparatus, and of the so-called first "selector-switch"; Fig. 2 being a diagrammatic representation of that portion of the apparatus known as a second "selector- 100

105

110

switch"; Fig. 3 being a diagrammatic representation of that portion of the switching apparatus known as the "connector-switch"; Fig. 4 being a diagrammatic representation 5 of the called subscriber's telephone and signaling equipment, and of the so-called first "selector-switch" allotted to the said called subscriber; Fig. 5 being a diagrammatic perspective view of the "first-selector"; Fig. 10 6 being a similar view of the "second-selector"; Fig. 7 being a similar view of the "connector"; and Fig. 8 being a simplified diagram showing the method of supplying talking current to the talking circuit formed 15 between the calling and called subscribers' stations.

As thus illustrated, it has been assumed that the subscriber's station A is numbered 3321, while the subscriber's station B is numbered 2241. In an exchange of this size, it 20 will be readily understood that the arrangement and division of switching apparatus, and of the line terminals, is of such character as to necessitate, or at least make desirable, the employment of the said first and 25 second "selector-switches", as will hereinafter more fully appear. With the particular arrangement shown, each so-called first "selector-switch" is allotted to a single subscriber's line, while the so-called "connector-switches" are common to the different subscribers. In other words, in the particular 30 system, in connection with which I have elected to illustrate my invention, there are as many so-called first "selector-switches" as there are subscribers; but the second "selector-switches" are common to the different subscribers, and are considerably less in 35 number than the total number of subscribers; 40 and the said so-called "connector-switches" are also considerably less in number than the total number of subscribers. In the arrangement shown, and as previously stated, a first "selector-switch" always receives at least the first impulse or impulses 45 representing the first digit of the called number—that is to say, this so-called first "selector-switch" does not operate until the calling subscriber actually begins the process 50 of calling the desired number, and not until the impulse or impulses representing at least the first digit of the called number traverse the line of the calling subscriber; and this 55 is thought to be the true sense or meaning of the term "first selector". Also, with the arrangement shown, the impulse or impulses representing the next digit of the called number may cause the so-called second "selector" to operate and accomplish the second 60 step in the process of connecting one subscriber's line with another. The impulses representing the last two digits of the called number are, however, received by and permitted to act upon the said "connector- 65 switch"; and in this way the said so-called

"connector-switch" constitutes the last element of the switching apparatus to be operated by the calling subscriber in establishing connection with the called subscriber's line. In a general way, the subscriber's equipment 70 at station A includes the usual transmitter and receiver, a call-bell, a hook-switch, and switching mechanism for calling and ringing any other subscriber of the exchange, as will hereinafter more fully appear; and this may 75 also be true of the apparatus at station B.

The first "selector" may be of any suitable known or approved construction, and may comprise the usual "vertical" and "rotary" relays 87 and 90, the bridge cut-off relay 51, 80 the "rotary" and "vertical" magnets 114 and 109, together with the "release" magnet 118 and "private" magnet 106. Other familiar features of a switch of this character consist of the rotary switch-shaft C, which is given 85 a step-by-step "vertical" movement by the "vertical" magnet 114, and a step-by-step "rotary" movement by the "rotary" magnet 109, through the medium of any suitable, known or approved mechanical connections. 90 This first "selector-switch" is also further identified by the circuit-changing arms 63, 64, 65, 66 and 67 comprised in a so-called "side-switch", and which are operated in the usual and well-known manner by the "private" magnet 106 through the medium of any suitable, known or approved mechanical connections. 95 In this "selector" the "side-switch" circuit-changing arm 64 has a new function, inasmuch as it cooperates with the wipers 126 in closing the circuit of the "release-magnet" 118, these additional wipers 126, having no other function than that of closing the "release-circuit", being new in a 100 switch of this character. 105

The second "selector" shown in Fig. 2 may also be of any suitable, known or approved construction. It may comprise the usual "vertical" and "rotary" relays 184 and 190, the usual "private-magnet" 500 for operating the so-called "side-switch," and the "side-switch" circuit-changing arms 147, 148, 149, 150 and 151. Other familiar elements of a second "selector" of this character consist of the "vertical magnet" 204 and the "rotary-magnet" 198, together with the "release-magnet" 143. The vertically movable and rotary switch-shaft D is of the usual construction, and may be operated in the usual or any other suitable manner by the said magnets 198 and 204, the mechanism of this second "selector," like that of the first "selector," operating on the well-known step-by-step principle. In this case, however the "side-switch" arm 148 has a new function, inasmuch as it cooperates with the shaft-wipers 207 in closing the "release-circuit"—that is to say, the circuit including the "release-magnet" 143. These additional 115 wipers 207, having no other function than 120 125 130

that of closing the "release-circuit," constitute an additional and new feature in a switch of this character.

The "connector" shown in Fig. 3 operates on the step-by-step principle, like the other switches, in a well-known manner, and may be of any suitable, known or approved character; but in this case certain novel circuit arrangements and features of construction are provided in addition to the elements or features usually found in a "connector-switch" of this character. For example, the said "connector" may comprise the usual "vertical" and "rotary" relays 225 and 235, the latter preferably of, say, 250 ohms resistance; the "release-magnet" 254, the ringing relay 301, and the "private-magnet" 329. Other familiar elements in a switch of this character consist of the "vertical" and "rotary" magnets 349 and 359, which are employed for operating the vertically-movable and rotary switch-shaft E, the latter being provided with the wipers 350, 360 and 361. The "connector" is further identified by the circuit-changing arms 322, 323, 324 and 325, of the "side-switch" that is operated by the "private-magnet" 329. There are also certain novel elements or features, however, included in the construction of the said "connector". For example, the differential "release-relay" F, used only by the called subscriber as a means of releasing the connections, constitutes a new feature in a "connector" of this character. The differential "release-relay" G, used only when the called subscriber fails to hang up his receiver, also constitutes a novel feature in a switch of this character. Other novel features consist of the impedance-coil 250, which is preferably of 250 ohms resistance; the "control-relay" H, which is only energized when the called subscriber answers; and certain novel circuit arrangements, as will hereinafter more fully appear.

One of the principal features of novelty, however, consists in the use of the said "connector" for supplying talking current to the talking circuit established between the two subscribers. The current for ringing the bell at the called subscriber's station comes from the ringing generator 294, as shown in Fig. 3. All other current, however—that is to say, the current for both talking and switching purposes—comes from the battery or centralized source of supply 61 at the central exchange. In the drawings, this battery is shown repeated, or in different places, for convenience of illustration, as this species of my invention is more easily illustrated than the single battery form; but it will be readily understood that one battery is preferably employed, and that its positive pole is grounded. Consequently, the current for operating the different relays and magnets all comes from the centralized source of

supply, and current from this same source is then fed through the "connector" to the talking circuit as soon as the connection is completed between the two subscribers' lines, and the called subscriber answers. In other words, and during conversation between the two subscribers, the current necessary for talking purposes is fed to this circuit from the battery 61 through the coils of relays F and H, and through the "side-switch" arms 324 and 325 and the shaft-wipers 360 and 361 to the line of the called subscriber; the condensers 267 and 276, located in opposite sides of the talking circuit, preventing a flow of battery current in the opposite direction. At the same time, and owing to the energizing of the relay H, current is supplied to the other part of the talking circuit—that is to say, back to the calling subscriber—from the battery 61 through the coils of relay G, and through impedance 250 to one side of the circuit, and through the "rotary-relay" 235 to the other side of the circuit. In this way, and during the time that the subscribers are talking, the battery 61 is bridged across the talking circuit at points on each side of the condensers 267 and 276. And as the "control-relay" H is only energized when the called subscriber answers, as, for example, by removing his receiver, it is evident that no closed metallic battery circuit exists until the called subscriber answers; and for this reason no talking current is furnished from the battery to the talking circuit until both subscribers are using their telephones. As shown, one battery furnishes talking current to the calling subscriber, and another battery furnishes talking current to the called subscriber; and the battery for the called subscriber energizes the means by which the other battery is bridged across the circuit to supply current to the calling subscriber. As stated, these two batteries are preferably one, although for certain purposes, like long distance work, I may use two batteries, as shown. In other words, the centralized source of current supply can be made up of several batteries or sections. The first "selector" shown in Fig. 4, and allotted to the subscriber's apparatus at station B is, of course, similar to that shown in Fig. 1. In Fig. 4, however, the first "selector" is not in use, while that shown in Fig. 1 is in use; and at this juncture it will be seen that the second "selector" shown in Fig. 2 is also in use, and that the "connector" shown in Fig. 3 is in use. Throughout the different portions of the diagram showing the connection between the two subscribers, the dark or heavy lines represent the subscribers' line-conductors, and also the trunk-line conductors, constituting the talking circuit. At the subscribers' stations, the arrangement is preferably such that the switch-hook

39, for example, will close together the contacts 7, 8 and 9 when the receiver is replaced, but not when the receiver is removed. In other words, these contacts 7, 8 and 9 are brought together for the purpose of releasing the different switches after the subscribers have finished their conversation, and are used for no other purpose.

Having thus described in a general way both the construction and the operation of my improved central-energy automatic telephone system, the details of construction, and the functions of the different elements, will be best understood by considering the various operations and circuit connections which take place in connecting one subscriber's line with another.

Suppose, for example, that sub-station #3321 desires connection with sub-station #2241. The calling subscriber will first remove the receiver 22 from switch-hook 39, which act opens contacts 24 and 10 and closes contacts 3 and 4. The subscriber will then, by means of any suitable calling device, twice close and break contact-point 37 with contact 35, thereby twice establishing momentarily, and twice sending an electrical current impulse over, the circuit from ground 1, through conductor 2, contacts 3 and 4, conductors 15, 20 and 40, contacts 35 and 37, conductors 41 and 48, circuit-changing switch-arm 66, circuit-changing switch-point 77, conductor 102, electro-magnetic relay 87, conductor 86, contact 54, armature 52, conductors 55 and 60, battery 61, conductor 62 to ground 1. This causes the electro-magnetic relay 87 to attract its armature, close and break contacts 88 and 91 twice, thus momentarily closing the circuit from ground through conductor 93, contacts 91 and 88, conductor 104, armature 124, contact 123, conductors 121, 99 and 84, circuit-changing switch-arm 64, circuit-changing switch-point 71, conductor 96, electro-magnet 114, conductor 115, battery 61, conductor 116 to ground 1; and which operation, resulting in a vertical step-by-step motion of the wipers, will place the said wipers 126, 127, 128 and 129 before, but not in connection with, the second row of contacts leading to a second "selector-switch." After the two impulses are made as described, the calling device will cause connection to be made and broken between contact-points 34 and 36, thus establishing a circuit from ground 1, conductor 2, contact-point 3 with contact-point 4, conductors 15, 20 and 40, contact 34 with contact 36, conductors 42 and 49, circuit-changing switch-arm 67, circuit-changing switch-point 80, electro-magnetic relay 90, conductor 94, contact 53, armature 52, conductors 55 and 60, battery 61, conductor 62 to ground 1. This operation causes the electro-magnetic relay 90 to attract its armature and close and break con-

tacts 89 and 92, thus establishing a circuit from ground 1, conductor 93, contacts 92 and 89, conductors 105 and 103, electro-magnetic relay 106, conductor 107, battery 61, conductor 108 to ground 1, causing electro-magnetic relay 106 to attract its armature, and causing armature 124 to engage contact 122, and breaking contact between armature 124 and contact-point 123. The construction of said electro-magnetic relay is such that, upon the attraction of its armature, and the release of same, the circuit-changing switch-arms 63, 64, 65, 66 and 67 are moved from contact-points 68, 71, 74, 77 and 80 to circuit-changing switch-contact-points 69, 72, 75, 78 and 81, respectively, thus establishing a circuit from ground 1, conductor 83, circuit-changing switch-arm 68, circuit-changing switch-contact-point 69, conductor 95, electro-magnet 109, conductor 111, armature 110, conductor 112, battery 61, conductor 113 to ground 1, causing electro-magnet 109 to attract its armature. In this way, the wiper-springs 126, 127, 128 and 129 are placed in contact with contact-points 130, 131, 132 and 133, thus establishing a circuit from ground 1, conductor 108, battery 61, conductor 107, electro-magnetic relay 106, conductor 103, circuit-changing switch-contact-point 75, circuit-changing switch-arm 65, conductors 85 and 100, wiper-spring 127, contact 131, conductor 135, which, if there be another switch in connection with contact-point 131, would complete circuit to ground, causing electro-magnetic relay 106 to hold its armature 124 in the attracted position, and thus holding the said circuit-changing switch-arms on the above-mentioned circuit-changing switch-contact-points 69, 72, &c., causing the armature of electro-magnet 109 to continue to vibrate by means of opening and closing the circuit of said electro-magnet at armature 110 and contact 112, which causes the wiper-springs to rotate until such time as a contact corresponding to 131 is found, to which no switch is connected. Upon the wiper-spring 127 closing this contact, the battery circuit through the private magnet or magnetic relay 106 is broken, allowing said relay to release its armature, which act causes circuit-changing switch-arms 63, 64, 65, 66 and 67 to move from contacts 69, 72, 75, 78 and 81 to circuit-changing switch-contacts 70, 73, 76, 79 and 82, thus grounding conductor 135 and contact-point 131 by means of the circuit from ground 1, circuit-changing switch-contact 76, circuit-changing switch-arm 65, conductors 85 and 100, wiper-spring 127, contact-point 131 to conductor 135, thus preventing the establishing of connection, by any other switch, of the wiper-spring 126 with contact 130; wiper-spring 127 with contact 131; wiper-spring 128 with contact 132; wiper-spring 129 with contact 133.

This also establishes connection from contact-point 37, conductors 41 and 48, circuit-changing switch-arm 66, contact-point 79, conductor 101, spring-wiper 128, contact 132, conductor 136, and a connection from contact 36, conductors 42 and 49, circuit-changing switch-arm 67, circuit-changing switch-point 82, conductor 125, wiper-spring 129, contact 133 to conductor 137, and connection from ground 1, conductor 120, battery 61, conductor 119, electro-magnet 118, conductors 117 and 97, circuit-changing switch-contact-point 73, circuit-changing switch-arm 64, conductors 84 and 99, wiper-spring 126 with contact 130 and conductor 134, which connects sub-station #3321 with the second "selector-switch" (Fig. 2) by means of conductors 134, 136 and 137, which connect sub-station #3321 with the trunks leading to the second thousand group of sub-stations. The subscriber at sub-station #3321 will then, by means of the calling device, close and break contacts 35 and 37 twice,—same as before,—thus sending momentarily electrical impulses from ground 1, conductor 2, contacts 3 and 4, conductors 15, 20 and 40, contacts 37 and 35, conductors 41 and 48, circuit-changing switch-arm 66, circuit-changing switch contact-point 79, conductor 101, wiper-spring 128, contact 132, conductor 136, circuit-changing switch-arm 150 (Fig. 2), circuit-changing switch contact-point 162, conductor 183, electro-magnetic relay 184, conductors 182, 194, battery 61, conductor 195, to ground 1, thus causing electro-magnetic relay 184 to attract its armature, causing contact-points 185 and 187 to be closed and opened twice, thus sending momentarily two impulses through electro-magnet 204 by means of the circuit from ground 1, conductor 189, contacts 187 and 185, conductor 173, relay-armature 174, contact 175, conductors 197 and 179, circuit-changing switch-arm 148, circuit-changing switch contact-point 156, conductor 178, electro-magnet 204, conductor 205, battery 61, conductor 206 to ground 1, which act by a resulting vertical step-by-step movement, places the wiper-springs 207, 208, 209 and 210 before, but not in contact with, contacts 211, 212, 213 and 214, respectively. As before mentioned, after the calling device has closed and broken the contacts 35 and 37 the required number of times, the contacts 34 and 36 are caused to be closed and opened, thus establishing, momentarily, a circuit from ground 1, conductor 2, contacts 3 and 4, conductors 15, 20 and 40, contacts 34 and 36, conductors 42 and 49, circuit-changing switch-arm 67, circuit-changing switch contact-point 82, conductor 125, wiper-spring 129, contact 133, conductor 137, circuit-changing switch-arm 151, circuit-changing switch contact-point 165, conductor 191, electro-magnetic relay 190, conductors 192 and 194, battery 61, conductor 195 to ground 1. This causes the electro-magnetic relay 190 to attract its armature, and closes contact 186 with contact 188, thus establishing a circuit from ground 1, conductor 189, contact 188 to contact 186, conductors 170 and 169, electro-magnetic relay 500, conductor 171, battery 61, conductor 172 to ground 1, which act causes electro-magnetic relay 500 to attract its armature; the construction of electro-magnetic relay 500 being such that, upon the attraction and release of its armature, the circuit-changing switch-arms 147, 148, 149, 150 and 151 break contact with circuit-changing switch contact-points 153, 156, 159, 162 and 165, and make contact with circuit-changing switch-contact-points 154, 157, 160, 163 and 166, respectively. Obviously, this establishes a circuit from ground 1, conductor 152, circuit-changing switch-arm 147, circuit-changing switch contact-point 154, conductor 177, electro-magnet 198, conductor 200, armature 199, contact-point 201, conductor 202, battery 61, conductor 203 to ground 1; the construction of electro-magnet 198 being such that, upon the vibration of its armature, the wiper-springs 207, 208, 209 and 210 are caused to be closed in contact with line-contacts 211, 212, 213 and 214. If there be another switch in connection with contact 212, there will then be established a connection from ground 1, conductor 172, battery 61, conductor 171, electro-magnetic relay 500, conductor 169, circuit-changing switch contact-point 160, side-switch-wiper 149 and conductor 180, wiper-spring 208, contact 212 to conductor 216 to ground 1, through the switch in connection with said contact 212 (not shown), which will cause the circuit-changing switch-arms to be held in contact with the circuit-changing switch contact-points last mentioned, causing electro-magnet 198 to continue to vibrate its armature until spring 208 reaches a contact-point similar to 212, but with which there is no switch connected. When the wiper reaches said contact 212, the electro-magnetic relay 500 releases its armature, thus causing, by electro-magnetic means, the circuit-changing switch-arms 147, 148, 149, 150 and 151 to break contact with contact-points 154, 157, 160, 163 and 166, and make contact with circuit-changing switch contact-points 153, 158, 161, 164 and 167, respectively, which breaks the circuit through electro-magnet 198, thus causing it to cease vibrating and allowing wiper-springs 207, 208, 209 and 210 to remain in contact with contact-points 211, 212, 213 and 214, thus establishing connection from sub-station #3321 (Fig. 1) with conductors 217 and 218, and also a connection from ground 1, circuit-changing switch contact-point 161, side-switch-wiper 149 and conductor 180, wiper-spring 208,

contact 212 to conductor 216, and a connection from ground 1 to conductor 145, battery 61, conductor 144, electro-magnetic relay 143, conductor 146, circuit-changing switch 5 contact-point 158, circuit-changing switch-arm 148, conductor 179, wiper-spring 207, contact 211 to conductor 215, and the establishing of connection between wiper-spring 208 and contact 212 with ground 1 prevents seizure of contacts in multiple with the contacts 212, 213 and 214, by any other switch.

A connection is thus established from telephone #3321 to conductors 217 and 218 15 (Fig. 3) leading to a "connector-switch" representing the one hundred group in which the connection is to be completed. The subscriber at sub-station #3321 will then, by means of the calling device, close 20 and break contacts 35 and 37 four times, thus sending momentary impulses from ground 1, conductor 2, contacts 3 and 4, conductors 15, 20 and 40, contacts 37 and 35; conductors 41 and 48, circuit-changing 25 switch-arm 66, circuit-changing switch contact-point 79, conductor 101, wiper-spring 128, contact 132, conductor 136, circuit-changing switch-arm 150 (Fig. 2), circuit-changing switch contact-point 164, conductor 181, wiper-spring 209, contact 213, conductors 217, 239 and 266 (Fig. 3), armature 265, contact 264, conductor 238, electro-magnetic relay 225, conductor 224, battery 61, conductor 219 to ground 1. This causes 30 electro-magnetic relay 225 to attract its armature, and thus close and break contact between contact-arm 227 and contact-point 231 four times; and each time this contact is closed a circuit is established from ground 35 1 through conductor 232, contact 231, contact-arm 227, conductor 221, armature 332, contact 331, conductor 326, circuit-changing arm 322, circuit-changing arm contact-point 335, conductor 347, electro-magnet 349, conductor 351, conductor 352, electric battery 61, conductor 354 to ground 1, thus causing electro-magnet 349 to attract its armature four times, which raises the wiper-springs 350, 360 and 361 before, but not in contact 40 with, contacts 495, 496 and 497, respectively. As before mentioned, after the calling device has closed and broken contacts 35 and 37 the required number of times, the contacts 34 and 36 are caused to be closed and 45 opened, thus establishing momentarily a circuit from ground 1, conductor 2 to contacts 3 and 4, conductors 15, 20 and 40, contacts 34 and 36, conductors 42 and 49, circuit-changing switch-arm 67, circuit-changing switch-arm contact-point 82, conductor 125, wiper-springs 129, contact 133, conductor 137, circuit-changing switch-arm 151 (Fig. 2), circuit-changing switch-arm contact-point 167, conductor 193, spring-wiper 50 210, contact 214, conductors 218 and 236

(Fig. 3), electro-magnetic relay 235, conductors 251 and 275, armature 274, contact-point 273, conductor 281, electric battery 61, conductor 282 to ground 1, thus completing the circuit and causing the electro-magnetic 70 relay 235 to momentarily attract its armature and thereby close and break contact between contact-arm 228 and contact-point 233. When this contact is made, a circuit is established from ground 1 through conductor 75 232, contact-point 233, contact-arm 228, conductor 222, electro-magnet 329, conductor 333, battery 61, conductor 334 to ground 1, thus causing electro-magnet 329 to momentarily attract its armature; and the construction of electro-magnet 329 is such that this causes circuit-changing switch-arms 325, 324, 323 and 322 to leave the contact-points 344, 341, 337 and 335 and pass to contact-points 345, 342, 338 and 336. The subscriber at sub-station #3321 will then, by means of the calling device, close and break contacts 35 and 37 once, the same as before, thus again sending, momentarily, an electrical impulse from ground 1, conductor 2, 80 contacts 3 and 4, conductors 15, 20 and 40, contacts 37 and 35, conductors 41 and 48, circuit-changing switch-arm 66, circuit-changing switch-arm contact-point 79, conductor 101, spring 128, contact 132, conductor 136, circuit-changing arm 150, circuit-changing arm contact-point 164, conductor 181, spring 209, contact 213, conductors 217, 239 and 266, armature 265, contact-point 264, conductor 238, electro-magnetic relay 225, conductor 224, battery 61, conductor 219 to ground 1; thus again causing electro-magnetic relay 225 to attract its armature momentarily, and again making and breaking contact between contact-arm 105 227 and contact-point 231. When this contact is made at this time, it completes the circuit from ground 1 through conductor 232, contact-point 231, contact-arm 227, conductor 221, armature 332, contact-point 331, 110 conductor 326, circuit-changing arm 322, contact-point 336, conductor 248, electro-magnet 359, conductor 353, conductor 352, battery 61, conductor 354 to ground 1, thus causing the electro-magnet 359 to momentarily attract its armature, which causes wipers 350, 360 and 361 to close contact with contacts 495, 496 and 497, respectively. As before mentioned, after the calling device has closed and broken contacts 35 and 37 115 the required number of times, contacts 34 and 36 are caused to be closed and opened, thus establishing, momentarily, a circuit from ground 1 to conductor 2, contacts 3 and 4, conductors 15, 20 and 40, contacts 34 120 and 36, conductors 42 and 49, circuit-changing switch-arm 67, circuit-changing switch contact-point 82, conductor 125, spring-wiper 129, contact 133, conductor 137, circuit-changing contact-arm 151 (Fig. 2), circuit- 125 130

changing arm-contact 167, conductor 193, restored to normal position; and circuit-spring-wiper 210, contact 214, conductors 218 and 236 (Fig. 3), electro-magnetic relay 235, conductors 251 and 275, armature 274, 5 contact-point 273, conductor 281, battery 61, conductor 282 to ground 1; thus again causing electro-magnetic relay 235 to momentarily attract its armature and close and break contact between contact-point 233 and contact-arm 228, and also between contact-point 234 and contact-arm 229. When contact is 10 made between contact-point 233 and contact-arm 228, the circuit is established from ground 1 through conductor 232, contact-point 233, contact-arm 228, conductor 222, electro-magnet 329, conductor 333, battery 61, conductor 334 to ground 1; thus causing electro-magnet 329 to momentarily attract its armature. The construction of electro-magnet 329 is such that if, at this time, no other switch be in connection with spring-wiper contact-points 495, 496 and 497, then, 15 when electro-magnet 329 releases its armature 332, circuit-changing arms 322, 323, 324 and 325 will pass from contact-points 336, 338, 342 and 345 to contact-points 339, 355, 343 and 346; but if some other switch should be in connection with spring-wiper contact-points 495, 496 and 497, then conductor 362 20 will be connected to ground 1 through the other switch by a circuit not shown; or if the subscriber at telephone #2241 should have, by operating the calling device, made a connection, or have begun to make a connection, to some other telephone, then contact-arm 409 (Fig. 4) will have broken contact from point 410, and have closed contact with contact-point 408; thus establishing a 25 circuit from ground 1 through conductor 411, contact-point 408, contact-arm 409, conductor 362 to contact 495 (Fig. 3), and connecting contact-point 495 to ground, as already mentioned. Contact-arm 409 is released by the "first-selector" as soon as its 30 shaft is raised one step. If contact-point 495 should be connected to ground, by either of the means already described, then when electro-magnet 329 attracts its armature circuit-changing contact-arms 322, 323, 324 and 325 will not pass from contact-points 336, 338, 342 and 345 to contact-points 339, 355, 343 and 346; but a circuit will be established from ground through conductor 362, contact 495, spring-wiper 350, conductor 340, circuit-changing arm 323, circuit-changing arm contact-point 338, conductor 237, contact-point 234, contact-arm 229, conductors 223 and 258, electro-magnet 254, conductor 256, battery 61, conductor 257 to 35 ground 1; thus causing electro-magnet 254 to attract its armature. The construction of the devices operated by this magnet is such that, when it attracts its armature, spring-wipers 350, 360 and 361 will break contact 40 from contacts 495, 496 and 497, and will be 40 restored to normal position; and circuit-changing arms 322, 323, 324 and 325 will pass from contact-points 336, 338, 342 and 345 to their original positions, making contact with points 335, 337, 341 and 344, respectively. The subscriber at telephone #3321 will, at this time, by means of a push-button on telephone #3321, press contact-arm 16 (Fig. 1) against contact-point 19 in an endeavor to ring the bell on telephone #2241; and when contact is closed between contact-arm 16 and contact 19, circuit will be established from ground 1, conductor 2, contact-arm 3, contact-point 4, conductor 15, contact-point 19 to contact-arm 16, conductor 365, contact-arm 6, contact-point 501, contact-arm 5, conductor 138, transmitter 14, conductors 13, 41 and 48, circuit-changing arm 66, circuit-changing arm-contact 79, conductor 101, spring-wiper 128, contact 132, conductor 136, circuit-changing arm 150 (Fig. 2), circuit-changing arm-contact 164, conductor 181, spring-wiper 209, conductors 213, 217, 239 (Fig. 3), conductor 266, armature 265, contact-point 264, conductor 238, electro-magnetic relay 225, conductor 224, battery 61, conductor 219 to ground 1; thus causing electro-magnetic relay 225 to attract its armature, and to make contact with contact-point 231 to 45 contact-arm 227, and thus establishing a circuit from ground 1 to conductor 232, contact-point 231, contact-arm 227, conductor 221, armature 332, contact-point 331, conductor 326, circuit-changing arm 322, circuit-changing arm contact-point 335, conductor 347, electro-magnet 349, conductors 351 and 352, battery 61, conductor 354 to ground 1. This causes electro-magnet 349 to attract its armature, and the construction of the devices operated by electro-magnet 349 is such that, when it attracts its armature, it causes the shaft to close contact between contact-arm 319 and contact-point 318; and when contact is made between contact-arm 319 and contact-point 318, this establishes a circuit which gives a "busy" signal to subscriber at telephone #3321 from ground 1 through conductor 308, conductor 314, induction-coil-winding 313, conductor 311, induction-coil 312, conductor 315, condenser 316, conductor 317, contact-point 318, contact-arm 319, conductor 321, circuit-changing arm contact-point 341, circuit-changing arm 324, conductor 327, armature 291, contact 290, conductor 289, condenser 267, conductors 239 and 217, contact 213 (Fig. 2), spring-wiper 209, conductor 181, contact 164, circuit-changing arm 150, conductor 136, contact 132 (Fig. 1), wiper 128, conductor 101, contact 79, circuit-changing arm 66, conductors 48, 41 and 13, transmitter 14, conductor 138, contact-arm 5, contact 501, contact-arm 25, receiver 22, conductor 21, coil 26, conductor 28, condenser 30, conductor 130, contact 125, contact 120, contact 115, contact 110, contact 105, contact 100, contact 95, contact 90, contact 85, contact 80, contact 75, contact 70, contact 65, contact 60, contact 55, contact 50, contact 45, contact 40, contact 35, contact 30, contact 25, contact 20, contact 15, contact 10, contact 5, contact 0.

ductors 32, 33, 42 and 49, circuit-changing arm 67, contact 82, conductor 125, wiper 129, contact 133, conductor 137, circuit-changing arm 151, contact 167, conductor 193, spring-wiper 210, contact 214, conductors 218 and 236 (Fig. 3), electro-magnetic relay 235, conductors 251 and 275, armature 274, contact 273, conductor 281, battery 61, conductor 282 to ground 1; thus completing a circuit for the signal-current induced by circuit-breaking mechanism 310, battery 61 and induction-coil-winding 313 in induction-coil-winding 312 through the receiver of telephone #3321, which gives the subscriber at telephone #3321 a signal informing him that telephone #2241 is busy.

If telephone #2241 is not busy, and conductor 362 is therefore not connected to ground (Fig. 4) at the time circuit-changing arms 322, 323, 324 and 325 are resting on contacts 336, 338, 342 and 345, and if at the same time electro-magnet 329 attracts its armature, then the construction of electro-magnet 329 is such that the circuit-changing arms 322, 323, 324 and 325 will pass from contact-points 336, 338, 342 and 345 to contact-points 339, 355, 343 and 346. The effect of this will be to complete a circuit from ground 1 through conductor 356, contact 355, circuit-changing arm 323, conductor 340, spring-wiper 350, contact 495 to conductor 362, thus establishing, on conductor 362, a guarding potential which will prevent any other switch (by means not here shown) from making a connection to conductor 362 until conductor 362 is again disconnected from ground. Completing the circuit from ground 1, this conductor 362 also establishes the circuit from ground to conductor 362, in the manner already described, and thence to contact-arm 409 (Fig. 4), contact 410, electro-magnetic relay 412, conductor 420, battery 61, conductor 421 to ground 1; thus causing the electro-magnetic relay 412 to attract its armature and open the contacts between armature 413 and contacts 414 and 415, and thus disconnecting the bridge between conductors 363 and 364 formed through circuit-changing arm 427, contact 440, conductor 451, electro-magnetic relay 449, conductor 418, contact 414, armature 413, contact 415, conductor 416, electro-magnetic relay 444, conductor 450, contacts 438 and 437, circuit-changing arm 426 to conductor 363. The signaling circuit is now established from telephone #3321 to telephone #2241, and subscriber at telephone #3321 can ring the bell 381 on telephone #2241 by closing contact between contact-arm 16 and contact-point 19 at telephone #3321 (Fig. 1). Momentarily closing this contact establishes a circuit from ground 1 through conductor 2, contact-arm 3, contact 4, conductor 15, contact 19, contact-arm 16, conductor 365, contact-arm 6, contact 501,

contact-arm 5, conductor 138, transmitter 14, conductors 13, 41 and 48, circuit-changing arm 66, contact 79, conductor 101, spring-wiper 128, contact 132, conductor 136, circuit-changing arm 150 (Fig. 2), contact 164, conductor 181, spring-wiper 209, contact 213, conductors 217 and 239 (Fig. 3), conductor 266, armature 265, contact 264, conductor 238, electro-magnetic relay 225, conductor 224, battery 61, conductor 219 to ground 1; thus momentarily establishing a circuit from battery through electro-magnetic relay 225 and causing it to attract its armature, closing circuit between contact 231 and contact-arm 227. The effect of closing contact 231 between contact 231 and contact-arm 227 will be to establish a circuit from ground 1 through conductor 232, contact 231, contact-arm 227, conductor 221, armature 332, contact-point 331, conductor 326, circuit-changing arm 322, contact 339, conductor 328, electro-magnetic relay 301, conductor 302, battery 61, conductor 303 to ground 1; thus establishing a circuit from battery 61 through electro-magnetic relay 301, causing it to attract its armatures and breaking connection between contact 290 and armature 291, and between contact 297 and armature 299, and to close contact from armature 291 to contact-point 292, and from armature 299 to contact-point 296. The effect of closing these contacts will be to ring the bell on telephone #2241, by completing the circuit from ringing machine 294 to conductor 293, contact 292, armature 291, conductor 327, circuit-changing arm 324, contact 343, conductor 357, spring-wiper 360, contact 496, conductors 363 and 406 (Fig. 4), conductor 502, vibrating bell 381, conductor 380, contact 375, contact-arm 376, conductor 391, condenser 397, conductors 400, 401, 407 and 364, contact 497 (Fig. 3), spring-wiper 361, conductor 358, contact 346, circuit-changing arm 325, conductor 300, armature 299, contact-point 296, conductor 295 to ringing machine 294. Upon receiving this signal the subscriber at telephone #2241 will remove the receiver from the switch-hook, thus allowing the hook to rise and to break contact between contact-point 375 and contact-arm 376, and to close contact between contact 372, contact-arm 373 and contact-arm 374; and the effect of closing these contacts will be to complete the circuit from battery through electro-magnetic relay-coils 268 and 269 (Fig. 3), causing them to attract their armatures, and through electro-magnetic relay-coils 286 and 287, but not causing them to attract their armatures because the coils 286 and 287 are so constructed as to neutralize each other. Circuit from battery through these coils comprises the following connections: from battery 61 through conductor 261, coil 268, conductor 280, coil 286, conductors 288 and 289, contact 290, arma-

ture 291, conductor 327, circuit-changing arm 324, conductors 343 and 357, spring-wiper 360, contact 496, conductors 363 and 406 (Fig. 4), conductor 382, transmitter 366, conductor 367, contact-arm 371, contact 372, contact-arm 373, conductor 393, contact-arm 385, contact 386, conductor 387, induction-coil 396, conductors 401, 407 and 364, contact 497 (Fig. 3), spring-wiper 361, conductor 358, contact 346, contact-arm 325, conductor 300, armature 299, contact 297, conductors 298 and 285, coil 287, conductor 279, coil 269, conductor 262, battery 61; thus completing a circuit through electro-magnetic coils 268, 269, 286 and 287, causing magnets 268 and 269 to attract their armatures, and also sending an electric current through transmitter 366 and induction-coil-winding 396 of telephone #2241 (Fig. 4); thus furnishing current for the talking circuit of telephone #2241. When coils 268 and 269 attract their armatures 265 and 274, contact is broken between armature 265 and contact-point 264, and established between armature 265 and contact-point 263; and contact is also broken between armature 274 and contact-point 273, and established between armature 274 and contact-point 272, thus completing a circuit from the battery 61 to electro-magnetic coils 245 and 270, furnishing electric current at telephone #3321 for the talking circuit. This circuit includes the following connections: battery 61, conductor 243, coil 270, conductor 247, contact 272, armature 274, conductors 275 and 251, electro-magnetic relay 235, conductors 236 and 218, contact 214, spring-wiper 210, conductor 193, contact-point 167, conductors 151 and 137, contact 133 (Fig. 1), spring-wiper 129, conductor 125, contact 82, circuit-changing arm 67, conductors 49, 42, 33 and 31, induction-coil-winding 27, conductor 18, contact 17, contact-arm 16, conductor 365, contact-arm 6, contact 501, contact-arm 5, conductor 138, transmitter 14, conductors 13, 41 and 48, circuit-changing arm 66, contact 79, conductor 101, spring-wiper 128, contact 132, conductor 136, circuit-changing arm 150, contact 164, conductor 181, spring-wiper 209, contact 213, conductors 217 and 239 (Fig. 3), conductor 266, armature 265, contact 263, conductor 259, impedance coil 250, conductor 246, coil 245, conductor 271 to the other terminal of the battery 61. It will be seen that the current supplied for talking purposes to the calling subscriber's line passes through three other coils—250 and 245 and 270—besides the coil 235, while the voltage of the common battery remains constant. This reduces the current through said coil to such an extent that the magnetic power developed therein is not sufficient to attract its armature against the tension of springs 228 and 229. Connections are now so completed

that subscriber at telephone #2241 can converse with subscriber at telephone #3321; and if subscriber at telephone #2241 should speak into the transmitter 366, variable resistances will be set up in the circuit just described from battery 61 through transmitter 366 and induction-coil-winding 396; and the effect of this will be to send variable currents through induction-coil-winding 396, thus inducing currents in induction-coil-winding 395. These variable currents will be carried to telephone #3321 over the following circuit, and also through the receiver of telephone #2241: induction-coil 395, conductor 389, receiver 394, conductor 392, contact-arm 374, contact-arm 373, contact 372, contact-arm 371, conductor 367, transmitter 366, conductors 382, 406, and 363, contact 496 (Fig. 3), spring-wiper 360, conductor 357, contact 343, circuit-changing arm 324, conductor 327, armature 299, contact 290, conductor 289, condenser 267, conductors 239 and 217, contact 213 (Fig. 2), spring-wiper 209, conductor 181, contact 164, circuit-changing arm 150, conductor 136, contact 132 (Fig. 1), spring-wiper 128, conductor 101, contact-point 79, circuit-changing arm 66, conductors 48, 41 and 13, transmitter 14, conductor 138, contact-arm 5, contact 501, contact-arm 6, contact-arm 25, conductor 23, receiver 22, conductor 21, induction-coil-winding 26, conductor 28, condenser 30, conductors 31, 33, 42 and 49, circuit-changing arm 67, contact 82, conductor 125, spring-wiper 129, contact 133, conductor 137, circuit-changing arm 151 (Fig. 2), contact 167, conductor 193, spring-wiper 210, contact 214, conductor 218, condenser 276 (Fig. 3), conductor 298, contact-point 297, armature 299, conductor 300, circuit-changing arm 325, contact-point 346, conductor 358, spring-wiper 361, contact 497, conductors 364 and 407 (Fig. 4), conductors 401 and 400, condenser 397, conductor 443 to the other end of induction-coil-winding 395, thus completing the circuit. Similarly, currents will be induced in the circuits just described between the two telephones passing through the receivers of both telephones if subscriber at telephone #3321 should speak into transmitter 14, thus causing variable resistance to be set up in the circuit already described from battery 61 through electro-magnetic relay-coils 245 and 270 (Fig. 3) to transmitter 14 and induction-coil-winding 27.

When conversation is completed between the subscribers at the two telephones, the switches may be restored to their normal positions in the following manner: The restoration of the switches is effected by subscriber at telephone #3321, or subscribers at both telephones #3321 and #2241, replacing their receivers on the switch-hooks, thus causing these hooks to return to nor-

mal position; but if subscriber at telephone #3321 should replace the receiver on the switch-hook first, then the restoration of the apparatus is effected in the following manner: As the switch-hook 39 on telephone #3321 (Fig. 1) returns to normal position, connection is made, momentarily, between contact-arm 7 and contact-points 8 and 9, thus completing a circuit from ground 1 to conductor 2, contact-arm 3, contact-point 4, conductors 15 and 20, contact-point 9, contact-arm 8, contact-arm 7, conductors 32, 33, 42 and 49, circuit-changing arm 67, contact-point 82, conductor 125, spring-wiper 129, contact 133, conductor 137, circuit-changing arm 151 (Fig. 2), contact 167, conductor 193, spring-wiper 210, contact 214, conductors 218 and 236 (Fig. 3), relay-coil 235, conductors 251 and 275, armature 274, contact-point 272, conductor 247, electro-magnetic relay-coil 270, conductor 248, battery 61, conductors 271 and 244 to ground 1; thus completing the circuit from battery 61 through electro-magnetic relay-coil 235, causing it momentarily to attract its armature, and also energizing coil 270, causing this coil to attract its armature 249, because electro-magnetic relay-coil 245 will no longer neutralize electro-magnetic relay-coil 270, inasmuch as the circuit, already described, through these coils, from battery 61 and through telephone #3321, was changed by both lines being momentarily grounded at telephone #3321 when the subscriber placed his receiver on the hook, thereby short-circuiting the coils 245 and 250 through ground, as follows: from ground 1 at station A to conductor 2, spring 3, contact-point 4, conductors 15 and 20, springs 9, 8 and 7 to conductor 13, spring 37, conductors 41 and 48, circuit-changing-arm 66, contact-point 79, conductor 101, wiper-spring 128, contact 132, conductor 136, circuit-changing-arm 150 (Fig. 2), contact-point 164, conductor 181, wiper-spring 209, contact 213, conductors 217, 239 and 266 (Fig. 3), armature 265, contact-point 263, conductor 259, coil 250, conductor 246, coil 245 to ground terminal 271 of battery 61. When coil 270 (Fig. 3) momentarily attracts its armature 249, contact is made between armature 249 and contact-point 241, thus momentarily establishing a circuit from ground 1 to conductor 242, armature 249, contact-point 241, conductors 240 and 238, electro-magnetic relay-coil 225, conductor 224, battery 61, conductor 219 to ground 1, and thus causing electro-magnetic relay-coil 225 to attract its armature and make connection between contact-arm 226 and contact-point 230, and also between contact-arm 227 and contact-point 231. Armature of electro-magnetic relay-coil 235 also being attracted at the same time, as just described, contact will be closed between contact-arm 228 and contact-point 233, thus completing a circuit from ground 1 to conductor 232, contact 233, contact-arm 228, conductor 222, electro-magnetic coil 329, conductor 333, battery 61, conductor 334 to ground 1, and thus completing a circuit from battery 61 through electro-magnetic relay-coil 329, causing it to attract its armature and break contact between armature 332 and contact-point 331, and to close contact between armature 332 and contact 330; thus completing a circuit from ground 1 through conductor 232, contact 231, contact-arm 227, conductor 221, armature 332, contact-point 330, conductors 223 and 258, electro-magnetic coil 254, conductor 256, battery 61, conductor 257 to ground 1, and causing electro-magnetic coil 254 to momentarily attract its armature 255. The construction of this coil 254 is such that, when it momentarily attracts its armature, the parts of the "connector-switch" (circuits of which are shown in Fig. 3) will be returned to their normal positions at the same time the circuits are momentarily closed, which will return the parts of the first and second "selectors" to their normal positions. This circuit is as follows: from ground 1 through conductor 252, contact-point 253, armature 255, conductor 248, contact-point 230, contact-arm 226, conductors 220 and 215, contact-point 211 (Fig. 2), spring-wiper 207, conductor 179, contact-arm 148, contact 158, conductor 146, coil 143, conductor 144, battery 61, conductor 145 to ground 1, thus momentarily closing circuit from battery 61 through electro-magnetic coil 143, causing it to momentarily attract its armature. The construction of coil 143 is such that, when it momentarily attracts its armature, the parts of the second "selector" (circuits of which are shown in Fig. 2) will be returned to their normal positions, and at the same time contact will be momentarily made between contact-point 142 and armature 141, thus completing the circuit from ground 1 through conductor 140, contact 142, armature 141, conductor 134, contact-point 130 (Fig. 1), spring-wiper 126, conductors 99 and 84, contact-arm 64, contact-point 73, conductors 97 and 117, electro-magnetic coil 118, conductor 119, battery 61, conductor 120 to ground 1, thus completing circuit from battery 61 through electro-magnetic coil 118, and causing it to momentarily attract its armature, which returns the parts of the first "selector-switch" to their normal positions. If the subscriber at telephone #2241 places the receiver on the switch-hook before subscriber at telephone #3321 has replaced the receiver, then, as the hook returns to normal position, breaking contact between contact-point 372, contact-arm 373 and contact-arm 374 (Fig. 4), it will thus break the circuit heretofore described from battery 61

through electro-magnetic coils 268 and 269 (Fig. 3), whereupon the armatures of these coils will return to normal positions, breaking contact between armature 265 and contact-point 263, and closing contact between armature 265 and contact-point 264, breaking contact between armature 274 and contact-point 272, and closing contact between armature 274 and contact-point 273. If armatures 265 and 274 should have returned to their normal positions before the subscriber at telephone #3321 replaces the receiver on the switch-hook, then the parts of the "connector-switch", instead of being restored to their normal positions by the closing of circuits as above described, will be restored by the closing of the following circuits: As the switch-hook on telephone #3321 descends, contact will be made, as already described, between contact-arm 7 and contact-points 9 and 8, thus closing circuit from ground 1 at telephone #3321 through both electro-magnetic relay-coils 225 and 235 (Fig. 3), causing them to momentarily attract their armatures. These circuits are as follows: from ground 1 (Fig. 1) through conductor 2, contact-arm 3, contact-point 4, conductors 15 and 20, contact-point 9, contact-arm 7, conductors 139, 13, 41 and 48, circuit-changing arm 66, contact 79, conductor 101, spring-wiper 128, contact 132, conductor 136, circuit-changing arm 150, contact 164, conductor 181, spring-wiper 209, contact 213, conductors 217 and 239 (Fig. 3), conductor 266, armature 265, contact-point 264, conductor 238, electro-magnetic relay-coil 225, conductor 224, battery 61, conductor 219 to ground 1, thus completing the circuit from battery 61 through coil 225, causing it to momentarily attract its armature, as already mentioned. The circuit through coil 235 is as follows: from ground 1 (Fig. 1) through conductor 2, contact-arm 3, contact 4, conductors 15 and 20, contact 9, contact-arm 7, contact-point 8, conductors 32, 33, 42 and 49, circuit-changing arm 67, contact 82, conductor 125, spring-wiper 129, contact 133, conductor 137, circuit-changing arm 151 (Fig. 2), contact 167, conductor 193, spring-wiper 210, contact 214, conductors 218 and 236 (Fig. 3), coil 235, conductors 251 and 275, armature 274, contact 273, conductor 281, battery 61, conductor 282 to ground 1, thus completing the circuit from battery 61 to coil 235. When coils 235 and 225 are thus momentarily energized at the same time, circuits are completed in the manner previously described, energizing coil 254 (Fig. 3), causing it to restore parts of the "connector-switch" to normal position, and also causing it to momentarily close circuit in the manner already described, which will cause parts of the first and second "selector-switches" to be restored to normal position. If operator

at telephone #3321 should neglect, for some time, to replace the receiver on the switch-hook, and thus fail to cause the parts of the first "selector", second "selector" and "connector" switches to be restored to their normal positions, the construction of the "connector-switch", and of telephone #2241, is such that the subscriber at telephone #2241 can then restore the parts of the "connector-switch" connected to the conductor to their normal positions, thus freeing the conductor and making it possible to call and to be called by other subscribers. This restoration of the parts of the "connector-switch" is effected as follows: By use of the calling device (not here shown) the subscriber at telephone #2241 (Fig. 4) can close contact between contact-arm 402 and contact-point 403, at the same time breaking contact between contact-point 372, contact-arm 373 and contact-arm 374; and when contact is broken between contact-point 372 and contact-arms 373 and 374, then the circuit previously described from battery 61 (Fig. 3) through coils 268, 269, 286 and 287 is open, and those coils are no longer energized, and, therefore, when contact 403 is closed with contact-arm 402 (Fig. 4), and the circuit is thus momentarily completed from battery through coil 287 (Fig. 3), this coil will momentarily attract its armature 283. The circuit from battery through coil 287 is as follows: from ground 1 (Fig. 4) through conductor 368 to contact-arm 369, contact 370, conductors 384, 390 and 398, contact 403, contact-arm 402, conductors 407 and 364, contact 497 (Fig. 3), spring-wiper 361, conductor 358, contact 346, circuit-changing arm 325, conductor 300, armature 299, contact-point 297, conductors 298 and 285, coil 287, conductor 279, coil 269, conductor 262, battery 61, conductors 261 and 260 to ground 1, thus completing the circuit already mentioned from battery 61 through coil 287, energizing this coil, and causing it to attract its armature 283; thus closing circuit from ground 1 through conductor 284, armature 283, contact 278, conductors 277, 223 and 258, coil 254, conductor 256, battery 61, conductor 257 to ground 1 and momentarily energizing coil 254 which, as already mentioned, is of such construction that, when it momentarily attracts its armature, parts of the "connector-switch" are restored to normal position. Among other things, spring-wiper 350 breaks contact with contact 495, thus breaking the circuit between ground 1 and conductor 362, and thus relieving conductor 362 of the guarding potential which was placed thereon at the time connection was completed between telephones #3321 and #2241. When this guarding potential is removed, conductor 362 is thus left open, so that con-

nections can be made to it by other "connector-switches"; and the circuit heretofore described from ground 1 through conductor 362, contact-arm 409 (Fig. 4), contact 410, 5 coil 412, conductor 420, battery 61, conductor 421 to ground 1 is also open, and the armature of coil 412 returns to normal position, thus again closing contact between armature 413 and contact-points 414 and 10 415, and again bridging the coils 444 and 449 across conductors 363 and 364, making it possible for subscriber at telephone #2241 to call any other subscriber.

It will thus be seen that an additional 15 trunk-line conductor is used, in conjunction with a fourth bank of contacts on each "selector", for releasing between switches. In this way, no part of the "release-circuit" 20 between switches includes any portion of the talking circuit, and consequently the bridges at the "selectors" are cut off or opened up during conversation between the subscribers, and are not at this time left across the circuit. For this reason, the talking circuit 25 includes no inductive resistance in the path of the talking currents, nor does it have any bridges at the "selectors". Of course, there are necessarily one or more bridges left across the talking circuit at the "connector"; 30 but even so, it will be seen that the number of bridges is reduced to a minimum in a system in which the talking circuit contains no inductive resistance or coils in the path of the talking currents—that is to say, no 35 inductive resistance or coils in series in the talking circuit at any points between the transmitting and receiving ends of the circuit. In other words, the additional wipers on the switch-shafts of the "selectors", and 40 additional bank of contacts in each "selector", have only one function, to wit, the closing of the "release-circuit" at certain normally open points. Furthermore, the 45 current, both for talking purposes and for operating the various relays and magnets included in the "selector" and "connector" switches, is all furnished from a battery or other common source of supply at the central station; and as a matter of special improvement, the current for talking purposes 50 is supplied to the circuit through the "connector", and through connections which are controlled by the called subscriber. In other words, the current for talking purposes is supplied to neither subscriber's line before 55 the called subscriber answers the call and completes the talking circuit by taking down his receiver. In this way, there is, as previously stated, no closed metallic circuit 60 until the called subscriber answers the call, and no flow of talking current in the circuit until everything is in readiness for its use by the two subscribers.

As shown in Figs. 1, 2 and 4, the "selectors" 65 are of the well-known and well-under-

stood type. For example, these "selectors" 70 may be of the general type shown and described in Patent No. 815,321, granted March 13, 1906, to Keith, Erickson and Erickson.

In Fig. 5, the "first-selector" is shown more in detail, and its general construction and operation are as follows: The shaft C, in addition to having the previously described shaft-wipers 126, 127, 128 and 129, 75 is also provided with the circular or so-called "vertical-ratchet-teeth" c, and with the longitudinal or so-called "rotary-ratchet-teeth" c¹, the latter being arranged immediately below the former. Just below the 80 said "rotary-ratchet-teeth", the shaft is also provided with a cam c² adapted, before the shaft rotates, to limit the movement of the "side-switch" when the latter makes the first step—that is, when the "side-switch-arm" c³ advances the previously described "side-switch-wipers" 63, 64, 65, 66 and 67 from their first or normal position to their second or intermediate position. The 85 "vertical-ratchet-teeth" c are provided with a longitudinally-extending groove or channel c⁴ adapted normally to engage the stationary rest or supporting-dog c⁵, the latter having a hook-shaped end portion adapted to project within said groove or channel. 90 With this arrangement, the said shaft can only move up and down while the said rest is in engagement with the said groove or channel; but the relative formation of the 95 said rest and "vertical-ratchet-teeth" is such that the shaft, when raised to any particular level, can then rotate in a step-by-step manner, its position at such level being maintained by the engagement of the end of the 100 rest with the under side of one of the ratchet-teeth—that is, when the shaft is 105 raised to the first level, the said rest then engages the under side of the first or uppermost ratchet-tooth when the shaft commences to rotate. Consequently, the shaft 110 is always positively supported by the said rest—when the shaft is elevated from its normal position—and regardless of the particular level at which the rotation is taking 115 place. The shaft-wiper 126 is adapted to engage any one of the one hundred contacts arranged in ten horizontal rows of ten contacts each in the "release-trunk-bank" c⁶. In a similar way, the so-called "private- 120 shaft-wiper" 127 is adapted to be brought into engagement with any one of the one hundred contacts arranged in ten horizontal rows of ten contacts each in the so-called "private-bank" c⁷. The wipers 126 and 127 are, of course, insulated from the shaft. The well-known "vertical" and "rotary" 125 "line-wipers" 128 and 129, mounted upon the said shaft and insulated from each other and also from the shaft, are adapted to engage any one of the one hundred, or 130

substantially one hundred, pairs of contacts arranged in ten horizontal rows of ten pairs each in the "line-bank" c^8 . In this "line-bank" c^8 , it will be understood that each 5 pair of contacts constitutes the terminal of a trunk-line leading to some other switch, such, for example, as the "second-selector" herein shown and described. The single contacts in the "private-bank" c^7 are each 10 multiplied, in the well-known or any suitable manner, with the corresponding "private-bank-contacts" of all other "first-selectors" having "line-terminals" corresponding to the trunk-line-terminals in the 15 bank c^8 . Each single contact or "release-trunk-terminal" in the bank c^8 is connected, by its allotted "release-trunk-line-conductor", with the switch-spring of the "release-magnet" of the "second-selector" to which 20 the corresponding trunk-line-conductors extend from the corresponding trunk-line-terminal in the bank c^8 . In this way, each "first-selector" is capable of making connection with any one of one hundred "second-selectors", and in each case its connection with a "second-selector" consists of two 25 parallel trunk-line-conductors to be used for talking, switching and signaling purposes, and of an additional or third trunk-line-conductor—the said "release-trunk"—to be 30 employed only as a part of the "release-circuit" for releasing the "first-selector", and which circuit is controlled by the so-called "release-magnet" of the "second-selector". In this way, the releasing is 35 accomplished neither through the medium of the main trunk-line-conductors, nor through the medium of the "private-bank-contacts". At its upper end, the said shaft is also provided 40 with a clock-spring device c^9 for returning it to its normal position after it has been released from any position to which it may have been rotated for the purpose of making the desired connection. It will also 45 be seen that this spring tends to hold the shaft in its normal position, said shaft being provided with the so-called and well-known normal post arm c^{10} adapted normally to bear against the stop or normal post c^{11} . 50 This normal post arm c^{10} is also adapted, when held in its normal position, to keep the switch-spring 45 out of engagement with the ground-contact 44, and in engagement with the contact 46, which latter, it will be 55 remembered, is connected directly with the bridge-cut-off-relay 51, whereby the latter is always energized through the so-called "private" shaft and "side-switch" wipers of any "connector" which makes connection 60 with the subscriber's line to which the said "first-selector" is allotted. This, of course, can only occur when the shaft C is in its normal position, and while the spring 45 is in engagement with the contact 46. 65 When the "first-selector" is used by the subscriber to whom it is allotted, its "side-switch" then performs the function of opening or cutting off the bridge in which are included the "line-relays" 87 and 90—that is, the "side-switch" cuts off these relays 70 when it advances from second to third position. The "vertical-magnet" 114 is provided with an armature c^{12} which is pivotally mounted at c^{13} , and thus adapted to swing about a horizontal axis. This armature 75 is provided with an arm c^{14} which carries a ratchet-pawl c^{15} , the latter being subject to the tension of the retracting-spring c^{16} and adapted to engage the "vertical-ratchet-teeth" c . Said arm is held in its normally 80 depressed position by any suitable spring means, such, for example, as the spring c^{17} , and is provided at its lower side with an L-shaped arm c^{18} . The construction is 85 such that the pawl c^{15} engages one of the ratchet-teeth c each time the armature c^{14} is attracted by the magnet 114, and is then disengaged from the ratchet-tooth and retracted away therefrom as soon as said magnet is de-energized. As is well known, the 90 "double-locking-dog" c^{19} is provided with a pair of prongs or locking dogs c^{20} and c^{21} adapted, respectively, to engage the said "vertical" and "rotary" ratchet-teeth carried by the shaft. This "double-locking-dog" is pivoted at c^{22} , and thus adapted to vibrate about a vertical axis for the purpose 95 of causing its prongs or locking-dogs to engage and disengage the ratchet-teeth on the shaft. As will be seen, this double locking-dog is normally out of engagement with said ratchet-teeth, and is only used for preventing back motion, either downward or rotatably, when the "selector" is being 100 operated, and while it is retained in its operative condition between subscribers' lines. For this reason, the "double-locking-dog" is provided with a projection c^{23} which is normally engaged by the apertured end portion of the "release-link" c^{24} , which latter 105 extends horizontally above the L-shaped arm c^{18} , and is rigid with the "release-magnet-armature" c^{25} . When the "vertical-magnet" 110 is energized, the link c^{24} is lifted out of engagement with the "double-locking-dog". It will be seen that this armature is adapted 115 to be attracted by the "release-magnet" 118, and is pivoted at c^{26} , so that it may vibrate about a horizontal axis. The said "double-locking-dog" is subject to the tension of a 120 spring c^{27} which tends to pull it into engagement with the ratchet-teeth on the shaft. A spring c^{28} is applied to the armature c^{25} , and tends normally to hold the latter away from its magnet, and in addition constitutes the means for positively 125 releasing the "double-locking-dog" from the ratchet-teeth on the shaft; and consequently the switch-shaft C is never released from any position to which it may have been 130

actuated until after the "release-magnet" 118 has been energized, and not until the latter has then become de-energized. In addition, the said "double-locking-dog" is 5 provided with a lower arm or finger c^{29} having a loose connection with the forward end of a horizontally-disposed restoring-link c^{36} , the latter having its other end pivotally connected with the finger c^{31} of the "side-switch" c^3 . With this arrangement, the said "double-locking-dog" can be drawn away from the ratchet-teeth without affecting the "side-switch"; but after the "side-switch" has been advanced to third position, or even to second position, the said "double-locking-dog" cannot be restored to its normal position away from said ratchet-teeth without incidentally or automatically restoring the said "side-switch" to its normal or first position. Said "side-switch" is pivoted at c^{32} , and is thereby adapted to vibrate about a vertical axis. As shown, the "side-switch" is subject to the tension of a spring c^{33} which tends to advance the 10 "side-switch-wipers" from their normal position to second and third positions. The means for operating the "side-switch" comprises the previously described "private-magnet" 106, said magnet being provided 15 with an armature c^{34} having pivotal points c^{35} , and thus adapted for vibration about a horizontal axis. The said armature is provided with a horizontally-disposed arm c^{36} which carries a couple of flat oppositely-arranged upper and lower springs c^{37} and c^{38} , said springs being provided at their end portions with saw-teeth, or ratchet-like teeth, c^{39} and c^{40} . These teeth are, it will 20 be readily understood, preferably not arranged exactly opposite to each other. Any suitable spring means, as, for example, the spring c^{41} , can be employed for holding the said arm c^{36} in its normally elevated position, and for holding the armature c^{34} normally away from its magnet 106. Under 25 such conditions, the "side-switch-finger" c^{42} is held normally in engagement with the innermost lower tooth c^{40} , and is then caused to engage the innermost upper tooth c^{39} when the armature c^{34} is attracted. Upon 30 the release of said armature, the finger c^{42} then escapes from between the two innermost teeth, permitting the "side-switch" to respond to the tension of the spring c^{33} ; but at this juncture it will be seen that the movement of the "side-switch" from first to second position, brought about by the energizing and de-energizing of the "private-magnet" 106, is limited by the engagement of the projection c^{43} with the outer edge of the cam c^2 , this projection being carried by the "side-switch" c^3 . The arm c^{36} is provided with a lateral switch-finger c^{44} adapted to manipulate the previously described switch-springs or switch-contacts 122, 123 35 and 124. The second time the magnet 106 is energized and then de-energized, the "side-switch" is thereby released from second to third position, and its motion this time is limited by the engagement of the finger c^{42} with the stationary or permanent stop c^{45} . The means for rotating the switch-shaft C comprise the previously mentioned "rotary-magnet" 109 provided with an armature c^{46} . This armature is pivoted at 40 c^{47} and thus adapted to vibrate about a vertical axis. As illustrated, a spring c^{48} is employed for keeping this "rotary-armature" normally away from its magnet 109. Said armature is provided with an arm c^{49} which carries a "rotary-ratchet-pawl" c^{50} adapted to engage the "rotary-ratchet-teeth" c^1 . This ratchet-pawl is subject to the tension of a spring c^{51} , and the construction is such that the pawl engages one of the 45 "rotary-ratchet-teeth" each time the "rotary-magnet" is energized, and then disengages the said teeth as soon as said magnet is de-energized. As previously described, the said "rotary-magnet" may have its armature provided with means for opening and closing its own circuit, so as to automatically keep up the rotation of the switch-shaft until an idle trunk-line is found. For 50 example, said armature may be provided with an arm c^{52} adapted to manipulate the previously described switch-contacts 110 and 112—that is, adapted to separate these contacts when the magnet 109 is energized, and to then allow the same to come together 55 when said magnet is de-energized. In addition, the said "rotary-magnet-armature" may be provided with an arm or finger c^{53} adapted to engage and operate the "private-magnet-armature" c^{54} , so as to enable the 60 "rotary-magnet" to accomplish or insure the actuation of the "side-switch" from second to third position. In other words, the "rotary-magnet", and not the "private-magnet", causes the operation of the "side-switch" 65 from second to third position in all cases where the first contact of any particular row or level is found idle and in all cases where the "private-magnet" is not energized and de-energized a second time by the engagement of the "private-wiper" with a busy contact—that is, a contact in the "private-bank" at which there is a guarding potential. Should the first contacts encountered by the 70 wipers be busy, so to speak, then the "private-magnet" is again energized, and finally de-energized as soon as a non-busy set of contacts is found, thus accomplishing the movement of the "side-switch" from second to third position. This in general is the 75 mechanical construction and mode of operation of a "first-selector", such as the one described in said previously mentioned patent, and the type which I preferably employ in my improved automatic common 80

battery telephone system; but it is obvious that other types of "selectors" may be employed, if such is desirable or necessary. The circuits and electrical operation of the 5 "selector" have been previously described in connection with the other diagrams. In Fig. 5 the parts of the "selector" are shown in their normal positions, whereas in Fig. 1 the "selector" is shown in the condition in 10 which it is temporarily maintained for the purpose of preserving the desired connection between the calling subscriber's line and the trunk-line-conductors leading to the "second-selector".

15 The "second-selector" shown in Fig. 6 is also of the type described and illustrated in said Patent No. 815,321, and is similar to the "selector" shown in Fig. 5. As this is a "second-selector," however, and one arranged at the end of a trunk-line, it does not require the bridge-cut-off-relay shown in connection with the "first-selector", and does not, of course, require any "line-normals", such, for example, as the "line" and "private" 20 normals 45⁴ and 47, as shown in Fig. 5, and which lead to the "line" and "private" bank-contacts of a certain number of "connectors", the contacts being multiplied together in any known or suitable manner. 25 As another distinction, the "second-selector" shown in Fig. 6 has its "release-magnet" 143 provided with the previously described and normally-separated switch-contacts 141 and 142, these contacts being brought together 30 by the energizing of said "release-magnet", and for the purpose previously explained. Otherwise, the construction and mode of operation of the said "second-selector" are substantially the same as the "first-selector", 35 and further description and explanation of the said "second-selector" will, therefore, be unnecessary. It may be stated, however, that the main trunk-line-conductors which terminate in its "line-bank" *d* are connected 40 at their other ends with the "side-switch-wipers" of "connectors", instead of "selectors", and that the "release-trunks" terminating in its "release-trunk-bank" *d*² extend to the said "connectors" instead of "selectors". 45 The contacts of the "private-bank" *d*² are multiplied with those of the "private-banks" of certain other "second-selectors" having multiples of the same trunk-lines, in the usual or any suitable manner.

50 In Fig. 6 the parts of the "second-selector" are shown in their normal positions, while in Fig. 2 the "second-selector" is shown in the condition in which it is temporarily maintained for the purpose of temporarily preserving the connection established between the first trunk-line and the second trunk-line running to the "connector".

55 The "connector" shown in Fig. 7, and which is of the type indicated in Fig. 3, is in

point of general construction and mode of operation substantially the same or quite similar to the "selectors". The "connector" illustrated is of the type shown and described in Patent No. 815,176, granted 70 March 13, 1906, to Keith, Erickson and Erickson. In Fig. 7, all of the parts of the "connector" are shown in their normal positions, whereas in Fig. 3 the "connector" is shown in the condition in which it exists after 75 it has made connection with the called subscriber's line, and just before the called subscriber answers. Like the "selector", the said "connector" has its rotary and vertically-movable switch-shaft *E* provided with 80 a stop-cam *e*, the "rotary-ratchet-teeth" *e*¹, the "vertical-ratchet-teeth" *e*², the latter having the longitudinal groove or channel *e*³ normally engaged by the rest or supporting-dog *e*⁴. Like a "selector", the said shaft 85 is always restored to its normal position by means of a clock-spring device *e*⁵, and is provided with a normal post arm *e*⁶ adapted normally to keep the switch-contact 319, 90 previously described, out of engagement with the contact 318, the latter being connected with the busy machine shown in Fig. 3, instead of with the "private-bank-contacts" of the "connector", as is true of the 95 "first-selector". The "vertical" and "rotary" ratchet-pawls *e*⁷ and *e*⁸ are similar to those described in connection with the "selectors", and are operated respectively by the "vertical" and "rotary" magnets 349 and 359, in the manner previously described, 100 and by constructions and arrangements similar to those which characterize the "selectors". The locking-dog *e*⁹ is similar to those employed in the "selectors", and has the previously described connection for restoring 105 the "side-switch" *e*¹⁰. This "side-switch", together with the means whereby it is operated by the previously described "private-magnet" 329, is similar to the "side-switch" arrangement included in the construction of the "selectors", and will be readily understood. The restoration of a "connector" to its normal position is, however, accomplished in a somewhat different manner from that employed in a "selector". 110 For example, the "release-magnet" 254 has its armature *e*¹¹ provided with an arm *e*¹² adapted to engage the locking-dog *e*⁹, and held normally away from the "release-magnet" by a spring *e*¹³. This armature is 115 adapted to close the normally-open and previously described contacts 255 and 253. As another distinction, the "release-link" *e*¹⁴ is pivotally mounted at *e*¹⁵ instead of being carried by the armature of the "release-magnet"; but like the "release-link" of the "selector", this link *e*¹⁴ has an aperture at its end adapted normally to engage a projection on the "double-locking-dog", so as to 120 normally hold the latter out of engagement 125 130

with the ratchet-teeth on the shaft E. In this way, the "connector" is released immediately upon the energizing of its "release-magnet", and without waiting for the de-energizing of the latter. On the other hand, it will be remembered that the "selectors" do not release until their "release-magnets" are de-energized by the separation of the contacts 255 and 253 in the "connector". As 10 another difference, it will be seen that a "connector" does not have its "rotary-magnet-armature" ^{e16} provided with means for operating the armature ^{e17} of the "private-magnet"; nor does it have any means for automatically opening and closing its own circuit, as is the case with the "rotary-magnet" of a "selector". Again, it will be seen that the "connector" is only provided with the "private-wiper" 350 and the two "line-wipers" 15 360 and 361, inasmuch as a "connector" does not need the additional or third shaft-wiper involved in the construction of the "selectors", and which are employed for cooperating with the third or "release-trunk-conductor" 20 for releasing between switches. The said third or additional "release-trunk-bank" of the "selectors", and their allotted shaft-wipers, constitute a feature of improvement in the said "selectors", and a part 25 of my invention, but are, of course, not necessary in the "connectors". Thus constructed, the "connector", unlike a "selector", is under the direct control of the calling subscriber throughout its entire selective 30 operation—that is, it is under the direct control of the calling subscriber while it is being used for selecting the proper group of subscribers, and is then operated by and under the direct control of the calling subscriber during its operation of selecting the 35 line of the called subscriber. If the called subscriber's line is busy, the "connector" releases automatically, in the manner previously described, and the calling subscriber 40 in then attempting to ring the called subscriber will do nothing more than give the shaft of the "connector" one or more vertical steps. Thus actuated, the "connector" simply establishes connection between the 45 "line" and the "busy" machine, thus automatically giving the calling subscriber the busy signal after it has refused to make connection with the subscriber's line which is already in use. A "connector" is, of course, 50 provided with the previously described ringer-relay 301, and is thus adapted to establish connection between the called subscriber's line and the ringing generator 55 294, in the manner previously set forth. And as a still further distinction, it will be seen that the trunk-line-conductors leading 60 to the "connector" terminate in the condensers 267 and 276, instead of in the "line-wipers" of the "side-switch", as is true of a 65 "selector". The "line-relays" 225 and 235

are bridged across the trunk-line at a point just outside of said condensers, with the middle point of the bridge—that is, between the two relays—connected to the non-grounded pole of the battery. It will be seen that the so-called "rotary-relay" 235 has one terminal permanently connected with the so-called "rotary-line-conductor" 218, while the corresponding terminal of the "vertical-line-relay" 225 is connected 75 with the so-called "vertical-line-conductor" 239 through the medium of the normally-closed contacts 264 and 265. In this way, the relay 225 is never disconnected from the non-grounded pole of the battery, but is 80 totally disconnected from the "vertical-line-conductor" 239 when the relay H is energized. On the other hand, the relay 235 is never disconnected from the "rotary-line-conductor" 218, but is disconnected from 85 the non-grounded pole of the battery when the said relay H is energized, but only for an instant, as its connection with the non-grounded pole of the battery is immediately re-established through the contacts 272 and 274 and the coil 270 of the relay G. With 90 this arrangement, the energizing of the relay H effects a substitution, so to speak, of the dead resistance 250 for the "line-relay" 225, thereby leaving the so-called "vertical-line-relay" 225 dead, or practically dead, so 95 to speak, during conversation between the two subscribers. It will be seen that the coils of the relays H and F are permanently 100 bridged across the "line-circuit" at a point between the condensers and the "side-switch-wipers" 324 and 325, with the battery included in series at the center of the bridge, as shown in Fig. 8. While the apparatus is in its normal condition, the relay G is totally disconnected from the 105 two sides of the trunk-line, and is only bridged across such line after the energizing of relay H, and during conversation between the two subscribers. Referring more 110 particularly to Fig. 8, it will be seen that the battery 61 is included in two bridges, when the talking-circuit is formed between subscribers' stations, each bridge including four coils. These coils, it will be understood, are so adjusted as to feed just the proper amount of battery current to the 115 talking-circuit, and are of sufficient inductive resistance to prevent a shunting or short-circuiting of the voice currents 120 through the battery. The relays G, H and F, together with the resistance-coil 250, are not found in the ordinary "connector"—that is, in the "connectors" of the type to 125 which my invention relates, and constitute matter of improvement. The method of operation, and the functions of the various coils, switch-contacts, etc., included in the construction of the "connector", have already been described and explained in con- 130

nection with Fig. 3 of the drawings. For this reason, further description of the "connector" mechanism and circuit arrangements shown in Fig. 7 will be unnecessary. It may be stated, however, that the one hundred pairs of contacts in the "line-bank" e^{18} are preferably each connected with a different subscriber's line, so that the "connector" may establish connection between its particular trunk-line and any one of one hundred subscribers' lines. And it will also be understood that the one hundred single contacts in the "private-bank" e^{19} are each multiplied with all corresponding "private-bank-contacts" in any and all other "connectors" having multiples of the different "line-contacts" in the "line-bank" e^{18} .

From the foregoing it will be seen that I provide an improved and highly efficient apparatus and circuit arrangement for effecting a distribution of switching and talking current from a centralized source of supply in a telephone system in which the connections between different subscribers' lines are accomplished automatically, so to speak, by the different subscribers, without the aid of the usual switchboard operators, and through the medium of electrically-actuated step-by-step selective switching machines arranged in suitable relation to each other at the exchange or central station.

As illustrated and as previously described, means are provided and arranged under the control of a calling subscriber for producing a call-signal at the called subscriber's station. Also, as illustrated, the called subscriber's line with which the "connector" has made connection is cut off from the common battery or centralized source of talking and switching current during the operation of ringing the called subscriber's bell, or producing any other suitable signal at the called subscriber's station. Of course, it is preferable to interpose the ringer-relay-springs between the called subscriber's line and the bridge through which battery current for talking purposes is supplied to the called subscriber's line—that is, to interpose the said ringer-relay-springs in the line or talking circuit at a point between the said bridge and the "side-switch-line-wipers." By this arrangement, it is possible to disconnect the said bridge and its battery from the called subscriber's line during the time the calling subscriber is causing ringing current to be projected over the called subscriber's line. In this way, the said ringing current cannot travel back over the trunk-lines to the calling subscriber's line, and cannot pass through the battery in bridge across the talking circuit. Thus the called subscriber controls the admission of talking current to both his line and the called subscriber's line, while the calling subscriber controls the admission of ringing current to

the called subscriber's line in such manner as to exclude it from all other circuits and lines.

It will be seen that I combine a trunk release for releasing between switches 70 with an independent busy-release for the connectors, which arrangement enables any connector to automatically release without releasing the selectors back of it. Furthermore, I combine with this arrangement a 75

busy-signal apparatus adapted to supply busy-signal current through the connectors to the calling telephone lines. It is evident that should the connectors, when automatically released, be allowed to close the trunk 80 release circuits back through the selectors, it would then be necessary to supply the busy-signal current directly through the first-selectors to the calling lines. This, of course, would result in a comparatively large 85

number of connections and additional parts, whereas with an arrangement by which the busy-signal can be applied through the connectors, a comparatively small amount of additional apparatus is necessary, inasmuch 90 as the connectors are, of course, less in number than the first-selectors or other suitable individual switches. The common battery has one pole grounded and the other pole normally connected with both sides of each 95

of the different telephone lines. As soon as the called subscriber answers, one side of the line circuit is then disconnected from the non-grounded pole of the battery and switched into direct connection with the 100 grounded pole of the same, thus temporarily bridging the battery across the talking circuit. Also, with my improved arrangement, a differential relay is employed by the calling subscriber in releasing the connections, and another differential relay is employed by the called subscriber for the same purpose. In this way, either the calling or the called subscriber can release the switches and connections, and in each case the release is 105 initiated over a grounded telephone line circuit, and by the unbalancing of a differential relay. In addition these differential relays serve as resistance for properly feeding the talking current to the lines, and as impedance for preventing a short-circuiting 110 of the voice-currents through the battery.

What I claim as my invention is:—

1. An automatic telephone system comprising subscribers' lines, means including a first "selector" and a second "selector" and a "connector" for automatically establishing connection between the calling and called subscribers' lines, and a battery at the central station connected to furnish talking current through the "connector" to the circuit completed between the two subscribers, the means for thus supplying talking current to the circuit being under the control 125 of the called subscriber only, whereby 130

- neither subscriber's station receives any talking current until the called subscriber answers the call.
2. An automatic telephone system comprising subscribers' lines, means for automatically connecting the calling subscriber's line with the called subscriber's line, said means including a "connector" for closing connection directly with the called subscriber's line, together with a centralized source of current for supplying talking current through the "connector" to the circuit completed between the subscribers, the flow of talking current through the talking circuit being under the control of the called subscriber only, whereby neither subscriber's station receives any talking current until the called subscriber answers the call.
3. An automatic telephone system comprising subscribers' lines, means including a plurality of step-by-step switching devices for automatically establishing connection between the calling and called subscribers' lines, together with a centralized source of current supply connected for supplying talking current through the last of said switching devices to both ends of the talking circuit, the flow of talking current through the talking circuit being under the control of the called subscriber only, whereby neither subscriber's station receives any talking current until the called subscriber answers the call.
4. An automatic telephone system comprising subscribers' lines, means including a first and second "selector" and a "connector" for automatically establishing connection between the calling and called subscribers' lines, said "connector" having a pair of relay-coils, and a centralized source of current supply at the central station connected to furnish talking current through said relay-coils to both ends of the talking circuit, the flow of talking current through the talking circuit being under the control of the called subscriber only, whereby neither subscriber's station receives any talking current until the called subscriber answers the call.
5. An automatic telephone system comprising subscribers' lines, means for automatically establishing connection between the calling and called subscribers' lines, said means including a "connector" for closing connection directly with the called subscriber's line, the said "connector" being provided with permanently bridged inductive resistance coils, armature means for said coils, line and local circuits controlled by said armature means, relay coils included in said line and local circuits, and a battery connected in the said bridge between said coils and adapted to furnish talking current to the called subscriber's line when the called subscriber answers the call, and to said line and local circuits to energize said coils.
6. An automatic telephone system comprising subscribers' lines, means for automatically establishing connection between the calling and called subscribers' lines, said means including a "connector" for closing connection directly with the called subscriber's line, together with a centralized source of current for supplying talking current through the "connector" to the circuit completed between the subscribers, the flow of talking current through the talking circuit being under the control of the called subscriber only, whereby neither subscriber's station receives any talking current until the called subscriber answers the call.
7. An automatic telephone system comprising subscribers' lines, step-by-step switching apparatus for automatically establishing connection between the calling and called subscribers' lines, and a centralized source of current-supply for furnishing current to the subscribers' lines for both talking and switching purposes, the means for initiating the flow of talking current in the completed circuit being under the control of the called subscriber only, whereby neither subscriber's station receives any talking current until the called subscriber answers the call.
8. An automatic telephone system comprising subscribers' lines, step-by-step switching apparatus for automatically establishing connection between the calling and the called subscribers' lines, a battery for furnishing current to the subscribers' lines for both talking and switching purposes, and means under the control of the called subscriber only for initiating a flow of talking current in the circuit completed between the two subscribers.
9. An automatic telephone system comprising calling and called subscribers' lines, and means under the control of the called subscriber only for furnishing talking current to the calling subscriber's line.
10. An automatic telephone system comprising calling and called subscribers' lines connected up for conversation, a condenser in each side of the talking circuit, and means under the control of the called subscriber only for furnishing talking current to the two subscribers' lines at opposite sides of said condensers.
11. An automatic telephone system comprising calling and called subscribers' lines connected up for conversation, one or more relay bridges located at the exchange and temporarily cut off from the talking circuit during conversation, the talking circuit being free from inductive resistance at points between the transmitting and re-

- ceiving ends of the circuit, and a centralized source of current-supply connected to furnish talking current to the subscribers' lines.
12. An automatic telephone system comprising calling and called subscribers' lines connected up for conversation, relays normally bridged across the talking circuit but detached therefrom during conversation, the talking circuit being free from inductive resistance in the path of the talking currents at points between the transmitting and receiving ends of the circuit, and a centralized source of current-supply connected for furnishing talking current to the subscribers' lines.
13. An automatic telephone system comprising subscribers' lines, relays normally bridged across each line, a talking circuit included in said lines, said talking circuit being at all times free from inductive resistance in the path of the talking currents at points between the transmitting and receiving ends of the circuit, means for cutting off or opening up the bridges in which said relays are located when the two lines are connected up for conversational purposes, and a centralized source of current-supply for furnishing talking currents to the subscribers' lines and for also furnishing the current necessary for operating the said relays before the bridges of the latter are cut off or opened up.
14. An automatic telephone system comprising a subscriber's line terminating in a first "selector", a trunk-line terminating in a second "selector", and another trunk-line terminating in a "connector", another subscriber's line, together with a grounded "release-circuit" for each "selector", the said "selectors" each having a switch-shaft provided with wipers included only in the "release-circuit" of the "selector" containing such shaft.
15. An automatic telephone system comprising a first "selector" having a vertically-movable and rotatable switch-shaft provided with six wipers, and having also a "release-circuit", the sole function of two of said wipers being to form a part of said "release-circuit".
16. An automatic telephone system comprising a second "selector" having a vertically-movable and rotatable switch-shaft provided with six wipers, and having also a "release-circuit", the sole function of two of said wipers being to form a part of said "release-circuit".
17. An automatic telephone system comprising a vertically-movable and rotatable switch-shaft actuated by electrically-operated step-by-step mechanism, and a "release-circuit" for effecting a restoration of said shaft to its normal position, said shaft being provided with a laterally-projecting and swinging switch-contact the sole function of which consists in serving as a part of said "release-circuit".
18. An automatic telephone system comprising a step-by-step switching device provided with a switch-shaft actuated by electrically-operated step-by-step mechanism, a "release-trunk" line-conductor, and a "release-circuit" for effecting a restoration of said shaft to its normal position and including said trunk-line-conductor, said shaft being provided with a switch-contact the sole function of which consists in closing connection directly with said trunk-line-conductor and thereby serving as a part of said "release-circuit".
19. An automatic telephone system comprising a "connector" provided with "vertical" and "rotary" relays and "vertical" and "rotary" magnets, a vertically-movable and rotary switch-shaft, circuit-changing arms operated by a "private-magnet", a "release-magnet", wipers on said shaft, bank-contacts adapted to cooperate with said wipers, a differentially-wound "release-relay" only used when the called subscriber fails to hang up his receiver, a "control-relay" only energized when the called subscriber answers the call, a differentially-wound "release-relay" used by the called subscriber to release the connections, and a centralized source of current-supply adapted to furnish current through the coils of said first-mentioned relays and the coils of said "control-relay" for both talking and switching purposes.
20. An automatic telephone system comprising a talking circuit, a "connector" in said circuit provided with a "rotary-relay", and a release-relay, a battery for furnishing talking current to the said circuit through the coils of said relays, together with a line-relay having a circuit controlled by said release-relay, and a release-circuit controlled by said line-relay.
21. An automatic telephone system comprising a talking circuit, a "connector" included in said circuit and provided with a "control-relay" energized only when the called subscriber answers the call, and a battery connected for furnishing talking current through the coils of said relay to the said circuit.
22. An automatic telephone system comprising a connector, a calling subscriber's line connected with a called subscriber's line through the medium of the "connector", said "connector" including a relay the energizing and de-energizing of which is under the control of the called subscriber exclusively, together with a common battery or suitable means for supplying current to the talking circuit, and connections whereby such current is furnished to the calling subscriber's station through stationary contacts of said

relay, and through the coils of said relay to the called subscriber's station.

23. An automatic telephone system comprising subscribers' lines, means for automatically connecting the calling subscriber's line with the called subscriber's line, said means including a "connector" for closing connection directly with the called subscriber's line, together with a centralized source of current for supplying talking current through the "connector" to the circuit completed between the subscribers, the flow of talking current through the talking circuit being under the control of the called subscriber only, whereby neither subscriber's station receives any talking current until the called subscriber answers the call, and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

24. An automatic telephone system comprising subscribers' lines, means including a plurality of step-by-step switching devices for automatically establishing connection between the calling and called subscribers' lines, together with a centralized source of current supply connected for supplying talking current through the last of said switching devices to both ends of the talking circuit, the flow of talking current through the talking circuit being under the control of the called subscriber only, whereby neither subscriber's station receives any talking current until the called subscriber answers the call, and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

25. An automatic telephone system comprising subscribers' lines, means including a first and second "selector" and a "connector" for automatically establishing connection between the calling and called subscribers' lines, said "connector" having a pair of relay-coils, and a centralized source of current supply at the central station connected to furnish talking current through said relay-coils to both ends of the talking circuit, the flow of talking current through the talking circuit being under the control of the called subscriber only, whereby neither subscriber's station receives any talking current until the called subscriber answers the call, and means under the control of a calling subscriber for temporarily disconnecting the

called subscriber's line from the common battery or centralized source of talking and switching current, and for then projecting ringing current onto the called subscriber's line for the purpose of producing an audible signal at the called subscriber's station.

26. An automatic telephone system comprising subscribers' lines, means for automatically establishing connection between the calling and called subscribers' lines, said means including a "connector" for closing connection directly with the called subscriber's line, the said "connector" being provided with permanently bridged inductive resistance-coils, and a battery connected in the said bridge between said coils and adapted to furnish talking current to the called subscriber's line when the called subscriber answers the call, and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

27. An automatic telephone system comprising subscribers' lines, means for automatically establishing connection between the calling and called subscribers' lines, said means including a "connector" for closing connection directly with the called subscriber's line, together with a battery for supplying current to the "connector" for both talking and switching purposes, said "connector" being provided with condensers located in opposite sides of the talking circuit, and also with a pair of bridges arranged across the talking circuit at opposite sides of said condensers, both of said bridges including said battery, but the bridge at the called subscriber's end of the circuit being permanently closed, while the bridge at the calling subscriber's side of the circuit is normally open and only closed when the called subscriber answers the call, and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

28. An automatic telephone system comprising subscribers' lines, step-by-step switching apparatus for automatically establishing connection between the calling and called subscribers' lines, and a centralized source of current-supply for furnishing current to the subscribers' lines for both talking and switching purposes, the means for initiating the flow of talking current in the completed circuit being under the control of

the called subscriber only, whereby neither subscriber's station receives any talking current until the called subscriber answers the call, and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

5 29. An automatic telephone system comprising subscribers' lines, step-by-step switching apparatus for automatically establishing connection between the calling and the called subscribers' lines, a battery for furnishing current to the subscribers' lines for both talking and switching purposes, and means under the control of the called subscriber only for initiating a flow of talking current in the circuit completed between the two subscribers, and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

10 30. An automatic telephone system comprising calling and called subscribers' lines, and means under the control of the called subscriber only for furnishing talking current to the calling subscriber's line, and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

15 31. An automatic telephone system comprising calling and called subscribers' lines connected up for conversation, a condenser in each side of the talking circuit, and means under the control of the called subscriber only for furnishing talking current to the two subscribers' lines at opposite sides of said condensers, and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

20 32. An automatic telephone system comprising calling and called subscribers' lines connected up for conversation, one or more bridges cut off from the talking circuit during conversation, the talking circuit being

free from inductive resistance at points between the transmitting and receiving ends of the circuit, and a centralized source of current-supply connected to furnish talking current to the subscribers' lines, and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

25 33. An automatic telephone system comprising calling and called subscribers' lines connected up for conversation, relays normally bridged across the talking circuit but detached therefrom during conversation, the talking circuit being free from inductive resistance in the path of the talking currents at points between the transmitting and receiving ends of the circuit, and a centralized source of current-supply connected for furnishing talking current to the subscribers' lines, and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

30 34. An automatic telephone system comprising subscribers' lines, relays normally bridged across each line, a talking circuit included in said lines, said talking circuit being at all times free from inductive resistance in the path of the talking currents at points between the transmitting and receiving ends of the circuit, means for cutting off or opening up the bridges in which said relays are located when the two lines are connected up for conversational purposes, and a centralized source of current-supply for furnishing talking currents to the subscribers' lines and for also furnishing the current necessary for operating the said relays before the bridges of the latter are cut off or opened up, and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

35 35. An automatic telephone system comprising a subscriber's line terminating in a "first-selector," a trunk-line terminating in a "second-selector," and another trunk-line terminating in a "connector," another subscriber's line, together with a grounded "release-circuit" for each "selector," the said "selectors" each having a switch-shaft pro-

vided with wipers included only in the "release-circuit" of the "selector" containing such shaft, and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

36. An automatic telephone system comprising a "first-selector" having a vertically-movable and rotatable switch-shaft provided with six wipers, and having also a "release-circuit," the sole function of two of said wipers being to form a part of said "release-circuit," and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

37. An automatic telephone system comprising a "second-selector" having a vertically-movable and rotatable switch-shaft provided with six wipers, and having also a "release-circuit", the sole function of two of said wipers being to form a part of said "release-circuit", and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

38. An automatic telephone system comprising a vertically-movable and rotatable switch-shaft actuated by electrically-operated step-by-step mechanism, and a "release-circuit" for effecting a restoration of said shaft to its normal position, said shaft being provided with a laterally-projecting and swinging switch-contact the sole function of which consists in serving as a part of said "release-circuit", and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

39. An automatic telephone system comprising a step-by-step switching device provided with a switch-shaft actuated by electrically-operated step-by-step mechanism, a "release-trunk" line-conductor, and a "release-circuit" for effecting a restoration of

said shaft to its normal position and including said trunk-line-conductor, said shaft being provided with a switch-contact the sole function of which consists in closing connection directly with said trunk-line-conductor and thereby serving as a part of said "release-circuit", and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

40. An automatic telephone system comprising a "connector" provided with "vertical" and "rotary" relays and "vertical" and "rotary" magnets, a vertically-movable and rotary switch-shaft, circuit-changing-arms operated by a "private-magnet", a "release-magnet", wipers on said shaft, bank-contacts adapted to cooperate with said wipers, a differentially-wound "release-relay" only used when the called subscriber fails to hang up his receiver, a "control-relay" only energized when the called subscriber answers the call, a differentially-wound "release-relay" used by the called subscriber to release the connections, and a centralized source of current-supply adapted to furnish current through the coils of said first-mentioned relays and the coils of said "control-relay" for both talking and switching purposes, and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

41. An automatic telephone system comprising a talking circuit, a "connector" in said circuit provided with a "rotary-relay", and a battery for furnishing talking current to the said circuit through the coil of said relay, and means under the control of a calling subscriber for temporarily disconnecting the called subscriber's line from the common battery or centralized source of talking and switching current, and for then projecting ringing current onto the called subscriber's line for the purpose of producing an audible signal at the called subscriber's station.

42. An automatic telephone system comprising a talking circuit, a differentially-wound "release-relay" included in the mechanism of a "connector," and a battery connected to furnish talking current through the coils of said relay to the said circuit, and means under the control of a calling subscriber for temporarily disconnecting the

5 called subscriber's line from the common battery or centralized source of talking and switching current, and for then projecting ringing current onto the called subscriber's line for the purpose of producing an audible signal at the called subscriber's station.

43. An automatic telephone system comprising a talking circuit, a "connector" included in said circuit and provided with a 10 "control-relay" energized only when the called subscriber answers the call, and a battery connected for furnishing talking current through the coils of said relay to the said circuit, and means under the control 15 of a calling subscriber for temporarily disconnecting the called subscriber's line from the common battery or centralized source of talking and switching current, and for then projecting ringing current onto the 20 called subscriber's line for the purpose of producing an audible signal at the called subscriber's station.

44. An automatic telephone system comprising a talking circuit, a "connector" included in said circuit and provided with a 25 permanently bridged differentially-wound "release-relay" to be used by the called subscriber in effecting a disconnection, and a battery included in said bridge adapted for 30 furnishing current through the coils of said relay to the said circuit for both talking and switching purposes, and means under the control of a calling subscriber for temporarily disconnecting the called subscriber's 35 line from the common battery or centralized source of talking and switching current, and for then projecting ringing current on to the called subscriber's line for the purpose of producing an audible signal at the called 40 subscriber's station.

45. An automatic telephone system comprising a "selector" provided with four banks of contacts, two of said banks being "line-contacts," the third bank consisting of 45 "private-contacts," and the fourth bank consisting of "release-trunk-contacts," together with a rotatable switch-shaft provided with wipers adapted to engage their respective banks of contacts, and means under the 50 control of a calling subscriber for temporarily disconnecting the called subscriber's line from the common battery or centralized source of talking and switching current, and for then projecting ringing current on 55 to the called subscriber's line for the purpose of producing an audible signal at the called subscriber's station.

46. An automatic telephone system comprising a connector, a calling subscriber's 60 line connected with a called subscriber's line through the medium of the "connector," said "connector" including a relay the energizing and de-energizing of which is under the control of the called subscriber exclusively, together with a common battery 65

or suitable means for supplying current to the talking circuit, and connections whereby such current is furnished to the calling subscriber's station through stationary contacts of said relay, and through the coils of 70 said relay to the called subscriber's station, and means under the control of a calling subscriber for temporarily disconnecting the called subscriber's line from the common 75 battery or centralized source of talking and switching current, and for then projecting ringing current onto the called subscriber's line for the purpose of producing an audible signal at the called subscriber's station.

47. An automatic telephone system comprising subscribers' lines, means including a "first-selector" and a "second-selector" and a "connector" for automatically establishing connection between the calling and called subscribers' lines, and a battery at the central 80 station connected to furnish talking current through the "connector" to the circuit completed between the two subscribers, the means for thus supplying talking current to the circuit being under the control of the 85 called subscriber only, whereby neither subscriber's station receives any talking current until the called subscriber answers the call, and means for temporarily disconnecting the called subscriber's line from the central 90 source of talking current during the operation of producing a call-signal at the called subscriber's station.

48. An automatic telephone system comprising subscribers' lines, means for automatically connecting the calling subscriber's line with the called subscriber's line, said means including a "connector" for closing connection directly with the called subscriber's line, together with a centralized 100 source of current for supplying talking current through the "connector" to the circuit completed between the subscribers, the flow of talking current through the 105 talking circuit being under the control of the called subscriber only, whereby neither subscriber's station receives any talking current until the called subscriber answers the call, and means for temporarily disconnecting the called subscriber's line from the central 110 source of talking current during the operation of producing a call-signal at the called subscriber's station.

49. An automatic telephone system comprising subscribers' lines, means including a plurality of step-by-step switching devices for automatically establishing connection between the calling and called subscribers' 115 lines, together with a centralized source of current-supply connected for supplying talking current through the last of said switching devices to both ends of the talking circuit, the flow of talking current through the talking circuit being under the 120 control of the called subscriber only, where- 125

- by neither subscriber's station receives any talking current until the called subscriber answers the call, and means for temporarily disconnecting the called subscriber's line from the central source of talking current during the operation of producing a call-signal at the called subscriber's station.
50. An automatic telephone system comprising subscribers' lines, means including a first and second "selector" and a "connector" for automatically establishing connection between the calling and called subscribers' lines, said "connector" having a pair of relay-coils, and a centralized source of current-supply at the central station connected to furnish talking current through said relay-coils to both ends of the talking circuit, the flow of talking current through the talking circuit being under the control of the called subscriber only, whereby neither subscriber's station receives any talking current until the called subscriber answers the call, and means for temporarily disconnecting the called subscriber's line from the central source of talking current during the operation of producing a call-signal at the called subscriber's station.
51. An automatic telephone system comprising subscribers' lines, means for automatically establishing connection between the calling and called subscribers' lines, said means including a "connector" for closing connection directly with the called subscriber's line, the said "connector" being provided with permanently bridged inductive resistance-coils, and a battery connected in the said bridge between said coils and adapted to furnish talking current to the called subscriber's line when the called subscriber answers the call, and means for temporarily disconnecting the called subscriber's line from the central source of talking current during the operation of producing a call-signal at the called subscriber's station.
52. An automatic telephone system comprising subscribers' lines, means for automatically establishing connection between the calling and called subscribers' lines, said means including a "connector" for closing connection directly with the called subscriber's line, together with a battery for supplying current to the "connector" for both talking and switching purposes, said "connector" being provided with condensers located in opposite sides of the talking circuit, and also with a pair of bridges arranged across the talking circuit at opposite sides of said condensers, both of said bridges including said battery, but the bridge at the called subscriber's end of the circuit being permanently closed, while the bridge at the calling subscriber's side of the circuit is normally open and only closed when the called subscriber answers the call, and means

for temporarily disconnecting the called subscriber's line from the central source of talking current during the operation of producing a call-signal at the called subscriber's station.

53. An automatic telephone system comprising subscribers' lines, step-by-step switching apparatus for automatically establishing connection between the calling and called subscribers' lines, and a centralized source of current-supply for furnishing current to the subscribers' lines for both talking and switching purposes, the means for initiating the flow of talking current in the completed circuit being under the control of the called subscriber only, whereby neither subscriber's station receives any talking current until the called subscriber answers the call, and means for temporarily disconnecting the called subscriber's line from the central source of talking current during the operation of producing a call-signal at the called subscriber's station.

54. An automatic telephone system comprising subscribers' lines, step-by-step switching apparatus for automatically establishing connection between the calling and the called subscribers' lines, a battery for furnishing current to the subscribers' lines for both talking and switching purposes, and means under the control of the called subscriber only for initiating a flow of talking current in the circuit completed between the two subscribers, and means for temporarily disconnecting the called subscriber's line from the central source of talking current during the operation of producing a call-signal at the called subscriber's station.

55. An automatic telephone system comprising calling and called subscribers' lines, and means under the control of the called subscriber only for furnishing talking current to the calling subscriber's line, and means for temporarily disconnecting the called subscriber's line from the central source of talking current during the operation of producing a call-signal at the called subscriber's station.

56. An automatic telephone system comprising calling and called subscribers' lines connected up for conversation, a condenser in each side of the talking circuit, and means under the control of the called subscriber only for furnishing talking current to the two subscribers' lines at opposite sides of said condensers, and means for temporarily disconnecting the called subscriber's line from the central source of talking current during the operation of producing a call-signal at the called subscriber's station.

57. An automatic telephone system comprising calling and called subscribers' lines connected up for conversation, one or more bridges cut off from the talking circuit during conversation, the talking circuit being

- free from inductive resistance at points between the transmitting and receiving ends of the circuit, and a centralized source of current-supply connected to furnish talking current to the subscribers' lines, and means for temporarily disconnecting the called subscriber's line from the central source of talking current during the operation of producing a call-signal at the called subscriber's station.
58. An automatic telephone system comprising calling and called subscribers' lines connected up for conversation, relays normally bridged across the talking circuit but detached therefrom during conversation, the talking circuit being free from inductive resistance in the path of the talking currents at points between the transmitting and receiving ends of the circuit, and a centralized source of current-supply connected for furnishing talking current to the subscribers' lines, and means for temporarily disconnecting the called subscriber's line from the central source of talking current during the operation of producing a call-signal at the called subscriber's station.
59. An automatic telephone system comprising subscribers' lines, relays normally bridged across each line, a talking circuit included in said lines, said talking circuit being at all times free from inductive resistance in the path of the talking-currents at points between the transmitting and receiving ends of the circuit, means for cutting off or opening up the bridges in which said relays are located when the two lines are connected up for conversational purposes, and a centralized source of current-supply for furnishing talking currents to the subscribers' lines and for also furnishing the current necessary for operating the said relays before the bridges of the latter are cut off or opened up, and means for temporarily disconnecting the called subscriber's line from the central source of talking current during the operation of producing a call-signal at the called subscriber's station.
60. An automatic telephone system comprising a subscriber's line terminating in a "first-selector," a trunk-line terminating in a "second-selector," and another trunk-line terminating in a "connector," another subscriber's line, together with a grounded "release-circuit" for each "selector," the said "selectors" each having a switch-shaft provided with wipers included only in the "release-circuit" of the "selector" containing such shaft, and means for temporarily disconnecting the called subscriber's line from the central source of talking current during the operation of producing a call-signal at the called subscriber's station.
61. An automatic telephone system comprising a "first-selector" having a vertically-movable and rotatable switch-shaft provided with six wipers, and having also a "release-circuit," the sole function of two of said wipers being to form a part of said "release-circuit", and means for temporarily disconnecting the called subscriber's line from the central source of talking current during the operation of producing a call-signal at the called subscriber's station.
62. An automatic telephone system comprising a "second-selector" having a vertically-movable and rotatable switch-shaft provided with six wipers, and having also a "release-circuit", the sole function of two of said wipers being to form a part of said "release-circuit", and means for temporarily disconnecting the called subscriber's line from the central source of talking current during the operation of producing a call-signal at the called subscriber's station.
63. An automatic telephone system comprising a vertically-movable and rotatable switch-shaft actuated by electrically-operated step-by-step mechanism, and a "release-circuit" for effecting a restoration of said shaft to its normal position, said shaft being provided with a laterally-projecting and swinging switch-contact the sole function of which consists in serving as a part of said "release-circuit", and means for temporarily disconnecting the called subscriber's line from the central source of talking current during the operation of producing a call-signal at the called subscriber's station.
64. An automatic telephone system comprising a step-by-step switching device provided with a switch-shaft actuated by electrically-operated step-by-step mechanism, a "release-trunk" line-conductor, and a "release-circuit" for effecting a restoration of said shaft to its normal position and including said trunk-line-conductor, said shaft being provided with a switch-contact the sole function of which consists in closing connection directly with said trunk-line-conductor and thereby serving as a part of said "release-circuit", and means for temporarily disconnecting the called subscriber's line from the central source of talking current during the operation of producing a call-signal at the called subscriber's station.
65. An automatic telephone system comprising a "connector" provided with "vertical" and "rotary" relays and "vertical" and "rotary" magnets, a vertically-movable and rotary switch-shaft, circuit-changing arms operated by a "private-magnet", a "release-magnet", wipers on said shaft, bank-contacts adapted to cooperate with said wipers, a differentially-wound "release-relay" only used when the called subscriber fails to hang up his receiver, a "control-relay" only energized when the called subscriber answers the call, a differentially-wound "release-relay" used by the called subscriber to release the connections, and a

- centralized source of current-supply adapted to furnish current through the coils of said first mentioned relays and the coils of said "control-relay" for both talking and switching purposes, and means for temporarily disconnecting the called subscriber's line from the central source of talking current during the operation of producing a call-signal at the called subscriber's station.
10. 66. An automatic telephone system comprising a talking circuit, a "connector" in said circuit provided with a "rotary-relay", and a battery for furnishing talking current to the said circuit through the coil of said relay, and means for temporarily disconnecting the called subscriber's line from the central source of talking current during the operation of producing a call-signal at the called subscriber's station.
15. 67. An automatic telephone system comprising a talking circuit, a differentially-wound "release-relay" included in the mechanism of a "connector", and a battery connected to furnish talking current through the coils of said relay to the said circuit, and means for temporarily disconnecting the called subscriber's line from the central source of talking current during the operation of producing a call-signal at the called subscriber's station.
20. 68. An automatic telephone system comprising a talking circuit, a "connector" included in said circuit and provided with a "control-relay" energized only when the called subscriber answers the call, and a battery connected for furnishing talking current through the coils of said relay to the said circuit, and means for temporarily disconnecting the called subscriber's line from the central source of talking current during the operation of producing a call-signal at the called subscriber's station.
25. 69. An automatic telephone system comprising a talking circuit, a "connector" included in said circuit and provided with a permanently bridged differentially-wound "release-relay" to be used by the called subscriber in effecting a disconnection, and a battery included in said bridge adapted for furnishing current through the coils of said relay to the said circuit for both talking and switching purposes, and means for temporarily disconnecting the called subscriber's line from the central source of talking current during the operation of producing a call-signal at the called subscriber's station.
30. 70. An automatic telephone system comprising a calling subscriber's line connected with a called subscriber's line through the medium of a "connector", said "connector" including a relay the energizing and de-energizing of which is under the control of the called subscriber exclusively, together with suitable means for supplying current to the talking circuit; and connections whereby such current is furnished to the calling subscriber's station through stationary contacts of said relay, and through the coils of said relay to the called subscriber's station, and means for temporarily disconnecting the called subscriber's line from the central source of talking current during the operation of producing a call-signal at the called subscriber's station.
35. 71. An automatic common battery telephone system comprising means under the control of a calling subscriber for disconnecting the called subscriber's line from the common battery during the operation of producing a call-signal at the called subscriber's station, together with means under the control of the called subscriber for determining the supply of talking current to both the calling and the called subscribers' stations, and whereby no talking current is furnished to either subscriber's station until the called subscriber answers.
40. 72. In a telephone exchange system, the combination of telephone lines, a common battery normally connected with said telephone lines, means for severing the normal connection between the battery and said lines, automatic connector-switches for use in connecting calling and called telephone lines together, means in said connectors for temporarily bridging said battery across the calling and called lines after the said normal connection has been severed, and subscribers' telephones connected in the telephone lines to receive talking current from said battery over said lines.
45. 73. In a telephone exchange system, the combination of telephone lines, trunk-lines, automatic switches, subscribers' devices for operating said switches over the telephone and trunk lines, trunk release circuits for releasing between switches, some of said switches being connectors, local busy release circuits for preventing any connector from seizing a busy telephone line, means for preventing the closure of the trunk release circuits when the busy release circuits are closed, and means by which the trunk release is initiated over the telephone and trunk lines, said trunk release circuits each including a third conductor of a trunk-line.
50. 74. In a telephone exchange system, the combination of telephone lines, selectors and connectors, trunk release circuits for releasing between switches, and independent busy release circuits for said connectors, whereby the connectors can release without releasing the selectors.
55. 75. In a telephone exchange system, a line, a battery having one pole grounded and the other pole normally connected with both sides of said line, a relay for temporarily disconnecting one side of the line and switching it into connection with the

5 grounded pole of the battery, said relay remaining energized during use of the line for talking purposes, a circuit for thus energizing said relay, and means by which a subscriber closes said circuit after the connection is established with the called line.

76. In a telephone exchange system, a line, a connector provided with a pair of line relays, a battery having one pole 10 grounded and the other pole normally connected with both sides of the line through the coils of said relays, a connector relay for temporarily disconnecting one side of said line and switching it into connection with the grounded pole of the battery, and means by which a subscriber controls said relay.

77. In a telephone exchange system, the combination of a line, a battery having one pole grounded and the other pole normally connected with both sides of said line, a relay for temporarily disconnecting one side of the line and switching it into connection with the grounded pole of the battery, said relay remaining energized during use of the line for talking purposes, a circuit for thus energizing said relay, means by which a subscriber closes said circuit after the connection is established with the called line, and a subscriber's telephone receiving talking 30 current from said battery.

78. In a telephone exchange system, the combination of selectors and connectors, telephone lines, trunk-lines, said selectors adapted to perform trunking operations in accordance with all except the last two digits of any called number, each selector having one motion to select groups and then rotary motion to automatically find an idle trunk in any selected group, said connectors each 40 adapted to connect with called telephone lines in accordance with the last two digits of any called number, a battery for operating said selectors and connectors, which connectors are less in number than the telephone 45 lines, and subscribers' telephones connected in the telephone lines to receive talking current from said battery.

79. In a telephone exchange system, the combination of telephone lines, automatic switches, a battery having one pole grounded, subscribers' telephones connected in the lines to receive talking current from said battery, differentially-wound release-relays for said switches, connectors by which each calling 55 telephone line receives talking current through the windings of a differential relay connected in series at opposite sides of said battery, and means for momentarily grounding each calling telephone line to unbalance the differential relay and thereby effect a disconnection from the called line.

80. In a telephone exchange system, the combination of telephone lines, automatic switches, a battery having one pole grounded, subscribers' telephones connected in the 65

lines to receive talking current from said battery, differentially-wound release relays for said switches, connectors by which each called telephone line receives talking current through the windings of a differential relay 70 connected in series at opposite sides of said battery, and means for momentarily grounding each called telephone line to unbalance the differential relay and thereby effect a disconnection from the calling line. 75

81. In a telephone exchange system, the combination of telephone lines, automatic switches, a battery having one pole grounded, subscribers' telephones connected in the lines to receive talking current from said 80 battery, differentially-wound release-relays for said switches, connectors by which each calling telephone line receives talking current through the windings of a differential relay 85 connected in series at opposite sides of said battery, means for momentarily grounding each calling telephone line to unbalance the differential relay and thereby effect a disconnection from the called line, together with trunk-lines, trunking switches, 90 and trunk release circuits by which the automatic switches control the release of the trunking switches.

82. In a telephone exchange system, the combination of telephone lines, automatic 95 switches, a battery having one pole grounded, subscribers' telephones connected in the lines to receive talking current from said battery, differentially-wound release-relays for said switches, connectors by which each 100 called telephone line receives talking current through the windings of a differential relay connected in series at opposite sides of said battery, means for momentarily grounding each called telephone line to unbalance the 105 differential relay and thereby effect a disconnection from the calling line, together with trunk-lines, trunking switches, and trunk release circuits by which the automatic switches control the release of the trunking 110 switches.

83. In a telephone exchange system, the combination of telephone lines, automatic switches, trunk-lines, trunk release circuits, each circuit including the third conductor 115 of one of said trunk-lines, connector-switches provided with means for controlling said circuits, means for automatically releasing only a connector to prevent seizure of a busy called telephone line, and automatic means for then supplying a busy-signal current through the released connector to the calling telephone line.

84. In a telephone exchange system, the combination of telephone lines, automatic 125 switches, trunk-lines, trunk release circuits, each circuit including the third conductor of one of said trunk-lines, connector-switches provided with means for controlling said circuits, means for automatically releasing 130

only a connector to prevent seizure of a busy called telephone line, and automatic means for then supplying a busy-signal current through the released connector to the calling telephone line, together with common battery transmitters connected in the telephone lines.

85. In a telephone exchange system, the combination of automatic switches, a talking circuit, a common battery, relay means controlling the flow of talking current from said battery to both ends of said talking circuit, and means at the called end of said talking circuit for controlling said relay means, whereby the talking circuit receives no talking current until the called subscriber answers.

86. In a telephone exchange system, telephone lines, switches individual thereto, automatic switches common thereto, telephone lines, and common means for supplying talking current through the switches to the telephone lines, said common switches controllable by the subscribers and less in number than the telephone lines, whereby the calling subscriber receives talking current through both individual and common switches.

87. In a telephone exchange system, the combination of telephone lines, relays normally disconnected from the lines, said relays being less in number than the telephone lines, automatic means for connecting the relays with the lines when the subscribers call, means for supplying talking current through the windings of said relays to the lines, and means controlled by said relays having one motion to select groups and then rotary motion to find a line in any selected group.

88. In a telephone exchange system, the combination of telephone lines, switches individual thereto, automatic switches having differential windings, and common means for supplying talking current through the differential windings to said lines, said automatic switches controllable by the subscribers and less in number than the telephone lines, whereby the calling subscriber receives talking current through both individual and common switches.

89. In a telephone system, automatic means for trunking between calling and called subscribers, and automatic means associated with said trunking means and controlled only by the called subscriber for supplying talking current to the substations of both calling and called subscribers.

90. In a telephone system, a calling telephone line, means for supplying talking current to the line, and automatic means controlled by the called subscriber for preventing a flow of talking current in the calling line until after the called subscriber answers.

91. In a telephone system, means for sup-

plying talking current, automatic means controllable only by the calling subscriber for finding the called line and automatic means controllable only by the called subscriber for initiating the flow of talking current to the calling subscriber.

92. In a telephone system, means for supplying talking current, a trunk line with inductive or reactive connections therein, a permanent bridge at one side of said connections, a normally open bridge at the other side of said connections, and means in the permanent bridge for closing the normally open bridge to initiate the flow of talking current to the calling subscriber.

93. In a telephone system, means for supplying talking current, a trunk line with inductive or reactive connections therein, a permanent bridge at one side of said connections, a normally open bridge at the other side of said connections, and means in the permanent bridge for closing the normally open bridge to initiate the flow of talking current to the calling subscriber, said means controlled only by the called subscriber.

94. In a telephone system, a line circuit, a battery having one pole grounded and the other pole normally connected with both sides of said circuit, means operated by current from the battery for extending the circuit in the direction of the called subscriber, and means operative only after the called line is found for bridging the battery across the line circuit.

95. In a telephone system, a line circuit, a battery having one pole grounded and the other pole normally connected with both sides of said circuit, means for transmitting ground impulses over one side and then the other of said line circuit, suitable devices responsive to said impulses for extending the said circuit in the direction of the called subscriber, means for retaining said battery in its normal relation to the line circuit until the called line is found, automatic electromagnetically-operated means for then switching the battery in bridge of said circuit, and a calling subscriber's telephone receiving talking current from said battery after the latter is bridged across the line circuit.

96. In a telephone system, a line circuit, a battery having one pole grounded and the other pole normally connected with both sides of said circuit, means operated by current from the battery for extending the circuit in the direction of the called subscriber, and means operative only after the called line is found for bridging the battery across the line circuit, said line circuit when extended including a trunk line across which the battery is bridged.

97. In a telephone system, a line circuit, a battery having one pole grounded and the other pole normally connected with both

105. A telephone system comprising calling and called lines, suitable means for furnishing current to the lines for talking purposes, and means operated by the flow of talking current in the called line for establishing the flow of such current in the calling line. 70
106. A telephone system comprising automatic means for finding a called line, suitable centralized means for furnishing current for talking purposes, and means operated by the flow of talking current in the called line for establishing the flow of talking current to the calling telephone. 75
107. A telephone system comprising conductors adapted to form a talking circuit, automatic switches for extending said conductors, a series of bridges across said conductors in certain of said switches, means for cutting off some of said bridges, means for supplying talking current through the remaining bridge or bridges to the conductors thus freed of one or more bridges, a trunk-release circuit and releasing means for certain of said switches operated thereby, and means in said remaining bridge or bridges for controlling said trunk-release circuit. 80
108. A telephone system comprising conductors adapted to form a talking circuit, automatic switches for extending said conductors, bridges across said conductors in certain of said switches, means for cutting off at least one of said bridges, means for supplying talking current to the circuit thus freed of all bridges except what is necessary for feeding the talking current, and a trunk-release circuit and release devices for certain of said switches operated thereby. 85
109. In a telephone system including automatic switches, the combination of a talking circuit, central means controlled by the called subscriber for supplying talking current to said circuit, and a trunk-release circuit and releasing means operated thereby. 100
110. In a telephone exchange system, the combination of telephone lines, a common battery normally connected with said telephone lines, means for severing the normal connection between the battery and said lines, automatic connector switches for use in connecting calling and called telephone lines together, provided with means having vertical motion to select groups and rotary motion to find the called line in any selected group, means in said connectors for temporarily bridging said battery across the calling and called lines after the said normal connection has been severed, and subscribers' telephones connected in the telephone lines to receive talking current from said battery over said lines. 115
111. In a telephone exchange system, the combination of telephone lines, trunk-lines, 120
105. sides of said circuit, means for transmitting ground impulses over one side and then the other of said line circuit, suitable devices responsive to said impulses for extending the said circuit in the direction of the called subscriber, means for retaining said battery in its normal relation to the line circuit until the called line is found, and automatic electromagnetically-operated means for then switching the battery in bridge of said circuit, said line circuit when extended including a trunk line across which the battery is bridged. 10
106. In a telephone system, a calling line and a called line, suitable means for furnishing current to said lines for talking purposes, and devices by which the called subscriber in answering establishes the flow of talking current in both lines. 15
107. In a telephone system, a calling line and a called line, suitable means for furnishing current to said lines for talking purposes, and devices controlled by the called subscriber in answering for establishing the flow of talking current in the calling line. 20
108. In a telephone system provided with connectors, a calling line and a called line, suitable means for furnishing current to said lines for talking purposes, and devices by which the called subscriber in answering establishes the flow of talking current in both lines, said devices including a relay in a connector at the central station of the called line. 25
109. In a telephone system provided with connectors, a calling line and a called line, suitable means for furnishing current to said lines for talking purposes, and devices responsive to the act of the called subscriber in answering for initiating and causing the flow of talking current in the calling line, said devices including a relay in a connector at the central station of the called line. 30
110. In a telephone system, a calling line and a called line, suitable means for furnishing current to said lines for talking purposes, and devices responsive to the act of the called subscriber in answering for initiating and establishing the flow of talking current in both lines, said devices including a relay at the central station of the calling line. 35
111. In a telephone system, a calling line and a called line, suitable means for furnishing current to said lines for talking purposes, and devices responsive to the act of the called subscriber in answering for establishing the flow of said current in the calling line, said devices including a relay at the central station of the calling line. 40
112. A telephone system comprising automatic means for trunking a calling line to a called line, suitable instrumentalities for furnishing talking current to the lines, and automatic means responsive to the called 45
113. In a telephone exchange system, the combination of telephone lines, trunk-lines, 50

- automatic switches, subscribers' devices for operating said switches over the telephone and trunk lines, some of said switches being connectors provided with means having vertical motion to select groups and rotary motion to find the called line in any selected group, trunk release circuits for releasing between switches controlled from said connector, local busy-release circuits for preventing any connector from seizing a busy telephone line, means for preventing the closure of said trunk-release circuits when the busy-release circuits are closed, and means by which the trunk-release is initiated over the telephone and trunk lines, said trunk-release circuits each including a third conductor of a trunk-line.
112. In a telephone exchange system, the combination of telephone lines, trunk selectors, connectors provided with means having vertical motion to select groups and rotary motion to find the called line in any selected group, trunk-release circuits controlled over said connectors for releasing between switches, and independent busy-release circuits for said connectors, whereby the connectors can release without releasing the selectors.
113. In a telephone exchange system, a line, a battery having one pole grounded and the other pole normally connected with both sides of said line, a connector provided with means having vertical motion to select groups and rotary motion to find the called line in any selected group, and a relay for temporarily disconnecting one side of the line and switching it into connection with the grounded pole of the battery, said relay energized during talking.
114. In a telephone exchange system, a line, a connector provided with means having vertical motion to select groups and rotary motion to find the called line in any selected group, provided also with a pair of line relays, a battery having one pole grounded and the other pole normally connected with both sides of the line through the coils of said relays, and a connector relay for temporarily disconnecting one side of said line and switching it into connection with the grounded pole of the battery.
115. In a telephone exchange system, the combination of a line, a battery having one pole grounded and the other pole normally connected with both sides of said line, a connector provided with means having vertical motion to select groups and rotary motion to find the called line in any selected group, and a relay for temporarily disconnecting one side of the line and switching it into connection with the grounded pole of the battery, together with a subscriber's telephone receiving talking current from said battery, said relay energized during talking.
116. In a telephone exchange system, the

combination of a line, a connector provided with means having vertical motion to select groups and rotary motion to find the called line in any selected group, provided also with a pair of line relays, a battery having one pole grounded and the other pole normally connected with both sides of the line through the coils of said relays, and a connector relay for temporarily disconnecting one side of said line and switching it into connection with the grounded pole of the battery, together with a subscriber's telephone receiving talking current from said battery.

117. In a telephone exchange system, the combination of trunk selectors, connectors provided with means having vertical motion to select groups and rotary motion to find the called line in any selected group, telephone lines, trunk-lines, said selectors adapted to perform trunking operations in accordance with all except the last two digits of any called number, said connectors adapted to connect with called telephone lines in accordance with the last two digits of any called number, a battery for operating said selectors and connectors, and subscribers' telephones connected in the telephone lines to receive talking current from said battery.

118. In a telephone exchange system, the combination of telephone lines, automatic switches, a battery having one pole grounded, subscribers' telephones connected in the lines to receive talking current from said battery, connectors provided with means having vertical motion to select groups and rotary motion to find the called line in any selected group, differentially-wound release relays for said connectors, means in said connectors by which each calling telephone line receives talking current through the windings of a differential relay connected in series at opposite sides of said battery, and means for momentarily grounding each calling telephone line to unbalance the differential relay and thereby effect a disconnection from the called line.

119. In a telephone exchange system, the combination of telephone lines, automatic switches, a battery having one pole grounded, subscribers' telephones connected in the lines to receive talking current from said battery, connectors provided with means having vertical motion to select groups and rotary motion to find the called line in any selected group, differentially-wound release relays for said connectors, means in said connectors by which each called telephone line receives talking current through the windings of a differential relay connected in series at opposite sides of said battery, and means for momentarily grounding each called telephone line to unbalance the dif-

differential relay and thereby effect a disconnection from the calling line.

120. In a telephone exchange system, the combination of telephone lines, automatic switches, a battery having one pole grounded, subscribers' telephones connected in the lines to receive talking current from said battery, connectors provided with differentially-wound release relays and means having vertical motion to select groups and rotary motion to find the called line in any selected group, means in said connectors by which each calling telephone line receives talking current through the windings of a differential relay connected in series at opposite sides of said battery, means for momentarily grounding each calling telephone line to unbalance the differential relay and thereby effect a disconnection from the called line, together with trunk-lines, trunking switches, and trunk-release circuits by which the automatic switches control the release of the trunking switches.

121. In a telephone exchange system, the combination of telephone lines, automatic switches, a battery having one pole grounded, subscribers' telephones connected in the lines to receive talking current from said battery, connectors provided with means having vertical motion to select groups and rotary motion to find the called line in any selected group, differentially-wound release relays for said connectors, means in said connectors by which each called telephone line receives talking current through the windings of a differential relay connected in series at opposite sides of said battery, means for momentarily grounding each called telephone line to unbalance the differential relay and thereby effect a disconnection from the calling line, together with trunk-lines, trunking switches, and trunk-release circuits by which the automatic switches control the release of the trunking switches.

122. In a telephone exchange system, the combination of telephone lines, automatic selector switches, trunk-lines, trunk-release circuits, each circuit including the third conductor of one of said trunk-lines, connector switches provided with means having vertical motion to select groups and rotary motion to find the called line in any selected group, provided also with means for controlling said circuits, means for automatically releasing only a connector to prevent seizure of a busy called telephone line, and automatic means for then supplying a busy-signal current through the released connector to the calling telephone line.

123. In a telephone exchange system, the combination of telephone lines, automatic selector switches, trunk-lines, trunk-release circuits, each circuit including the third conductor of one of said trunk-lines, connec-

tor switches provided with means having vertical motion to select groups and rotary motion to find the called line in any selected group, provided also with means for controlling said circuits, means for automatically releasing only a connector to prevent seizure of a busy called telephone line, and automatic means for then supplying a busy-signal current through the released connector to the calling telephone line, together with a common battery and common battery transmitters connected in the telephone lines.

124. In a telephone exchange system, the combination of automatic switches provided with means having vertical motion to select groups and rotary motion to find the called line in any selected group, a talking circuit, a common battery, relay means controlling the flow of talking current from said battery to both ends of said talking circuit, and means at the called end of said talking circuit for controlling said relay means, whereby the talking circuit receives no talking current until the called subscriber answers.

125. In a telephone exchange system, the combination of telephone lines, relays normally disconnected from the lines, automatic means for connecting the relays with the lines, provided with means having vertical motion to select groups and rotary motion to find the called line in any selected group, and means for supplying talking current through the windings of said relays to the lines.

126. In a telephone system, automatic means for trunking between calling and called subscribers, including switches provided with means having vertical motion to select groups and rotary motion to find the called line in any selected group, and automatic means associated with said trunking means and controlled only by the called subscriber for supplying talking current to the substations of both calling and called subscribers.

127. In a telephone system, a calling telephone line, switches provided with means having vertical motion to select groups and rotary motion to find the called line in any selected group, means for supplying talking current to the telephone lines, and automatic means controlled by the called subscriber for preventing a flow of talking current in the calling substation until after the called subscriber answers.

128. In a telephone system, automatic means controllable only by the calling subscriber for finding the called line having vertical motion to select groups and rotary motion to find the called line in any selected group, and automatic means controllable only by the called subscriber for initiating the flow of talking current to the calling subscriber.

129. A telephone system provided with means having vertical motion to select groups and rotary motion to find the called line in any selected group, a trunk-line with inductive or reactive connections therein, a permanent bridge at one side of said connections, a normally open bridge at the other side of said connections, and means in the permanent bridge for closing the normally open bridge to initiate the flow of talking current to the calling subscriber.

130. A telephone system provided with means having vertical motion to select groups and rotary motion to find the called line in any selected group, a trunk-line with inductive or reactive connections therein, a permanent bridge at one side of said connections, a normally open bridge at the other side of said connections, and means in the permanent bridge for closing the normally open bridge to initiate the flow of talking current to the calling subscriber, said means controlled only by the called subscriber.

131. In a telephone system, a line circuit, a battery having one pole grounded and the other pole normally connected with both sides of said circuit, means operated by current from the battery for extending the circuit in the direction of the called subscriber, provided with means having vertical motion to select groups and rotary motion to find the called line in any selected group, and means operative only after the called line is found for bridging the battery across the line circuit.

132. In a telephone system, a line circuit, a battery having one pole grounded and the other pole normally connected with both sides of said circuit, means for transmitting ground impulses over one side and then the other of said line circuit, suitable devices responsive to said impulses for extending the said circuit in the direction of the called subscriber, provided with means having vertical motion to select groups and rotary motion to find the called line in any selected group, means for retaining said battery in its normal relation to the line circuit until the called line is found, and automatic electromagnetically-operated means for then switching the battery in bridge of said circuit.

133. In a telephone system, a line circuit, a battery having one pole grounded and the other pole normally connected with both sides of said circuit, means operated by current from the battery for extending the circuit in the direction of the called subscriber, provided with means having vertical motion to select groups and rotary motion to find the called line in any selected group, means operative only after the called line is found for bridging the battery across the line circuit, and a calling subscriber's telephone re-

ceiving talking current from said battery after the latter is bridged across the line circuit.

134. In a telephone system, a line circuit, a battery having one pole grounded and the other pole normally connected with both sides of said circuit, means for transmitting ground impulses over one side and then the other of said line circuit, suitable devices responsive to said impulses for extending the said circuit in the direction of the called subscriber, provided with means having vertical motion to select groups and rotary motion to find the called line in any selected group, means for retaining said battery in its normal relation to the line circuit until the called line is found, automatic electromagnetically-operated means for then switching the battery in bridge of said circuit, and a calling subscriber's telephone receiving talking current from said battery after the latter is bridged across the line circuit.

135. In a telephone system, a line circuit, a battery having one pole grounded and the other pole normally connected with both sides of said circuit, means operated by current from the battery for extending the circuit in the direction of the called subscriber, provided with means having vertical motion to select groups and rotary motion to find the called line in any selected group, and means operative only after the called line is found for bridging the battery across the line circuit, said line circuit when extended including a trunk-line across which the battery is bridged.

136. In a telephone system, a line circuit, a battery having one pole grounded and the other pole normally connected with both sides of said circuit, means for transmitting ground impulses over one side and then the other of said line circuit, suitable devices responsive to said impulses for extending the said circuit in the direction of the called subscriber, provided with means having vertical motion to select groups and rotary motion to find the called line in any selected group, means for retaining said battery in its normal relation to the line circuit until the called line is found, and automatic electromagnetically-operated means for then switching the battery in bridge of said circuit, said line circuit when extended including a trunk-line across which the battery is bridged.

137. A telephone system provided with means having vertical motion to select groups and rotary motion to find the called line in any selected group, a calling line and a called line, suitable means for furnishing current to said lines for talking purposes, and devices by which the called subscriber in answering establishes the flow of talking current in both lines.

138. A telephone system provided with means having vertical motion to select groups and rotary motion to find the called line in any selected group, a calling line and a called line, suitable means for furnishing current to said lines for talking purposes, and devices controlled by the called subscriber in answering for establishing the flow of talking current in the calling line.
139. A telephone system provided with connectors having vertical motion to select groups and rotary motion to find the called line in any selected group, a calling line and a called line, suitable means for furnishing current to said lines for talking purposes, and devices by which the called subscriber in answering establishes the flow of talking current in both lines, said devices including a relay in a connector at the central station of the called line.
140. A telephone system provided with connectors having vertical motion to select groups and rotary motion to find the called line in any selected group, a calling line and a called line, suitable means for furnishing current to said lines for talking purposes, and devices responsive to the act of the called subscriber in answering for initiating and causing the flow of talking current in the calling line, said devices including a relay in a connector at the central station of the called line.
141. A telephone system provided with means having vertical motion to select groups and rotary motion to find the called line in any selected group, a calling line and a called line, suitable means for furnishing current to said lines for talking purposes, and devices responsive to the act of the called subscriber in answering for initiating and establishing the flow of talking current in both lines, said devices including a relay at the central station of the calling line.
142. A telephone system provided with means having vertical motion to select groups and rotary motion to find the called line in any selected group, a calling line and a called line, suitable means for furnishing current to said lines for talking purposes, and devices responsive to the act of the called subscriber in answering for establishing the flow of said current in the calling line, said devices including a relay at the central station of the calling line.
143. A telephone system comprising automatic means for trunking a calling line to a called line, provided with means having vertical motion to select groups and rotary motion to find the called line in any selected group, suitable instrumentalities for furnishing talking current to the lines, and automatic means responsive to the called subscriber for establishing the flow of such current in the calling line.
144. A telephone system provided with means having vertical motion to select groups and rotary motion to find the called line in any selected group, comprising calling and called lines, suitable means for furnishing current to the lines for talking purposes, and means operated by the flow of talking current in the called line for establishing the flow of such current in the calling line.
145. A telephone system comprising apparatus provided with means having vertical motion to select groups and rotary motion to find the called line in any selected group, suitable centralized means for furnishing current for talking purposes, and means operated by the flow of talking current in the called line for establishing the flow of talking current to the calling telephone.
146. A telephone system provided with means having vertical motion to select groups and rotary motion to find the called line in any selected group, comprising a talking circuit, a series of bridges across the conductors comprising said circuit, means for cutting off some of said bridges, means for supplying current through the remaining bridge or bridges to the circuit thus freed of one or more bridges, a trunk-release circuit and releasing means operated thereby, and means in said remaining bridge or bridges for controlling said trunk-release circuit.
147. A telephone system provided with means having vertical motion to select groups and rotary motion to find the called line in any selected group, comprising a talking circuit, bridges across the conductors comprising said circuit, means for cutting off at least one of said bridges, means for supplying talking current to the circuit thus freed of all bridges except what is necessary for feeding the talking current, and a trunk-release circuit and release devices operated thereby.
148. A telephone system provided with means having vertical motion to select groups and rotary motion to find the called line in any selected group, a talking circuit, bridges across the conductors comprising said circuit, means for supplying talking current to said circuit, automatic means for freeing the conductors of all bridges except what is necessary for feeding the talking current, and a trunk-release circuit and releasing means operated thereby.
149. A telephone system provided with means having vertical motion to select groups and rotary motion to find the called line in any selected group, a talking circuit, means controlled by the called subscriber for supplying talking current to said circuit, and a trunk-release circuit and releasing means operated thereby.
150. In a telephone system in which the subscribers are divided into groups, trunk selectors, an automatic connector switch pro-

- vided with means having motion in one direction to select groups and rotary motion to then find the line of the called subscriber in any selected group, and instrumentalities 65 for supplying talking current through said connector switch to the two connected substations.
151. In a telephone system in which the subscribers are divided into groups, trunk 10 selectors, an automatic connector switch provided with means having motion in one direction to select groups and rotary motion to find the line of the called subscriber in any selected group, and means including a 15 bridge in the said connector switch for supplying talking current therefrom to the line of the called subscriber.
152. In a telephone system in which the subscribers are divided into groups, trunk 20 selectors, an automatic connector switch provided with means having motion in one direction to select groups and rotary motion to find the line of the called subscriber in any selected group, and means including a 25 bridge in the said connector switch for supplying talking current therefrom to the line of the calling subscriber.
153. In a telephone system, switches for establishing talking circuits between calling 30 and called subscribers, means at the central station for supplying talking current to the substations, means for automatically reducing the number of bridges across the conductors forming any common battery talking circuit for certain of said switches, and 35 means including a trunk release circuit for releasing the connection and restoring the disconnected bridge or bridges.
154. In a telephone system, switches for establishing talking circuits between calling 40 and called subscribers, means at the central station for supplying talking current to the substations, means in certain of said switches for automatically selecting an idle trunk in 45 a predetermined group, means for automatically reducing the number of bridges across the conductors forming any common battery trunking circuit thus established between calling and called subscribers, and means for 50 automatically releasing the connection and restoring the disconnected bridge or bridges.
155. In a telephone exchange system, a subscriber's line, selector switches controlled thereby to connect with other lines, a 55 connector switch controlled through said selector switches, a pair of bridged magnets with a bridged battery in the calling end of said connector switch, a differential relay in the answering end of the same switch, an operating relay also in the answering end of the switch bridged with a grounded battery between ground and one limb of the line, and connections such that when the magnets in the calling end of the switch respond to the 60 act of the called subscriber in answering, they will disconnect the operating relay from the switch trunk wires and place it under the control of the differential relay, at the same time connecting the differential relay to the trunk wires, substantially as 65 described.
156. In an automatic telephone exchange system, a subscriber's metallic circuit and a connector switch controlled thereover, means at the subscriber's station for grounding one 70 side or the other of the line, a controlling magnet in the connector connected to one side of the line and a grounded battery, means for disconnecting the same from the line in completing a connection with another 75 line, and a magnet and a bridged battery thereby connected across the calling line, said magnet normally irresponsive to current from said bridged battery when the line is free from grounds but becoming responsive when the same is grounded to operate the controlling magnet and release the switch mechanism, substantially as 80 described.
157. A common battery automatic telephone exchange system comprising a connector provided with a pair of line-relays and a differential-relay, and a trunk-release-circuit for said connector, said release-circuit having normally-open switch-points 85 controlled by said line and differential relays.
158. A common battery automatic telephone exchange system comprising a selector provided with a release-relay, a connector provided with a pair of line-relays and a differential-relay, and a trunk-release energizing circuit for said release-relay, said circuit having normally-open switch-points 90 controlled by said line-relays and said differential-relay.
159. In a telephone exchange system substantially as disclosed, the combination of a connector provided with a pair of line-relays and a differential-relay, a trunk release circuit for said connector, said release circuit having normally open switch points 95 controlled by said line and differential relays, and subscribers' impulse transmitters or calling devices for transmitting to the exchange or central station the electrical impulses representing the number of any called subscriber.
160. In a telephone exchange system substantially as disclosed, the combination of a selector provided with a release relay, a connector provided with a pair of line relays and a differential relay, a trunk release energizing circuit for said release relay, said circuit having normally open switch points 100 controlled by said line relays and said differential relay, and subscribers' impulse transmitters or calling devices for 105

transmitting to the exchange or central station the electrical impulses representing the number of any called subscriber.

161. In a common battery automatic telephone exchange system, the combination of 5 a connector provided with a pair of line-relays and a differential-relay, a trunk-release-circuit for said connector, said release-circuit having normally-open switch-points controlled by said line and differential relays, subscribers' common battery transmitters adapted to receive talking current from the exchange or central station with which the same are connected, and subscribers' 10 ringing-keys associated with the said transmitters, together with means whereby the manual operation of any particular ringing-key temporarily opens the talking circuit through its allotted transmitter and 15 grounds one side of the line-circuit to produce an audible signal at the station of any called subscriber.

162. In a common battery automatic telephone exchange system, the combination of 20 a selector provided with a release-relay, a connector provided with a pair of line-relays and a differential-relay, a trunk-release energizing circuit for said release-relay, said circuit having normally-open switch-points controlled by said line-relays and said differential-relay, subscribers' common battery transmitters adapted to receive talking current from the exchange or central station with which the same are connected, and subscribers' 25 ringing-keys associated with the said transmitters, together with means whereby the manual operation of any particular ringing-key temporarily opens the talking circuit through its allotted transmitter and grounds one side of the line-circuit to produce an audible signal at the 30 station of any called subscriber.

163. The combination, in a common battery automatic telephone exchange system, 45 of a connector provided with a pair of line-relays and a differential-relay, a trunk-release-circuit for said connector, said release-circuit having normally-open switch-points controlled by said line and differential relays, subscribers' receivers and hook-switches, the latter operated by the taking down and hanging up of said receivers, and connections whereby the hanging up of any calling subscriber's receiver momentarily 50 connects his line to ground for the purpose of automatically releasing and restoring such line to normal condition.

164. The combination, in a common battery automatic telephone exchange system, 60 of a selector provided with a release-relay, a connector provided with a pair of line-relays and a differential-relay, a trunk-release energizing circuit for said release-relay, said circuit having normally-open switch-points controlled by said line-relays 65

and said differential-relay, subscribers' receivers and hook-switches, the latter operated by the taking down and hanging up of said receivers, and connections whereby the hanging up of any calling subscriber's 70 receiver momentarily connects his line to ground for the purpose of automatically releasing and restoring such line to normal condition.

165. The combination, in a common battery automatic telephone exchange system, 75 of a selector having release mechanism, a connector provided with a plurality of relays controllable by any calling subscriber using the connector, said connector having 80 release mechanism, and there being a trunk-release-circuit extending between the selector and the connector for controlling the release thereof, said release-circuit having a plurality of normally-open switch-points 85 controlled by the said calling subscriber's relays of the connector, subscribers' receivers and hook-switches, the latter operated by the taking down and hanging up of said receivers, and connections whereby the hanging up of any calling subscriber's receiver 90 momentarily connects his line to ground for the purpose of automatically releasing and restoring such line to normal condition.

166. In a telephone system, a plurality of 95 lines, selectors less in number than said lines, trunk lines divided into groups, said selectors having vertical motion to select groups and rotary motion to select an idle line in a selected group, means for selecting 100 idle selectors including a bridge normally closed across each line, means for supplying talking current to the line, and means for automatically opening or cutting off the bridges on the calling and called lines to 105 prevent short circuiting of the talking current.

167. In a telephone system, the combination of a connector provided with a back bridge relay having two windings, a battery permanently connected to one of said windings, the other winding being permanently connected to ground, a back bridge permanently including said windings, and means for energizing said relay by the closure of the called telephone line circuit. 110

168. A common battery automatic telephone exchange system, comprising a line circuit provided with inductive devices dividing the line circuit into inductively connected portions having a relay provided with normally closed contacts controlling the continuity of one of said portions of the line circuit, means for controlling said relay from a distant station, and a line circuit for energizing said relay. 120

169. In a telephone system, a plurality of subscribers' lines, a connector switch for connecting with any one of said lines, a line relay for controlling the operation of said 130

- connector, and a second relay in said connector controlling the circuit of said line relay, said second relay controlled by the called subscriber.
- 6 170. In a telephone system, a plurality of subscribers' lines, a connector switch for connecting with any one of said lines, a line relay for said connector controlling the operation thereof, a back bridge relay under 10 the control of the called subscriber, and means whereby said back bridge relay controls the energizing circuit of said line relay.
171. In a telephone system, a first circuit, a second circuit, a relay in said first circuit, 15 a relay in said second circuit, condensers for inductively connecting said circuits, and means under the control of said second relay for increasing the impedance of said first circuit by adding another relay.
- 20 172. In a telephone system, a first circuit, a second circuit, a relay in said first circuit, a relay in said second circuit, condensers for inductively connecting said circuits, means under the control of said second relay 25 for increasing the impedance of said first circuit by adding another relay therein, and means under the control of said first relay for controlling said second circuit.
173. In a telephone system, the combination 20 of trunk lines, automatic trunk selec-
tors, automatic connector switches for seizing the called subscriber's line, provided with means having vertical motion to select groups, and rotary motion to connect with a line in the selected group, means controlled 35 at the connectors for supplying talking current to the calling and called subscribers' lines, and trunk release circuits for the selectors controlled by the connectors.
174. In a telephone system, a line, a telephone for talking over said line, a switch, a group of lines, a relay in said switch, means for moving said switch, said switch controlled by said relay and said means whereby a connection may be extended from the first line to any line in the group, and means for supplying current for talking purposes to said telephone through the winding of said relay while the connection is maintained.
175. In a telephone system, a calling and 40 a called line, a central source of current for talking purposes, means comprising a progressively movable switch controlled over the calling line for finding the called line, and means for then automatically releasing said switch if the called line is busy.

Signed by me at Chicago, Cook County, Illinois, this 30th day of Dec., 1904.

ALFRED H. DYSON.
